UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 25, 1921. Serial No. 487,520.

To all whom it may concern:

Be it known that I, ALBEN E. LUNDELL, a citizen of the United States, residing at New York, in the county of Bronx, State 5 of New York, have invented certain new and useful Improvements in Telephone-Exchange Systems, of which the following is a full, clear, concise, and exact description.

This invention relates to automatic telephone exchange systems, and more particularly to exchange systems of large capacity.

It is the object of this invention to provide an improved full automatic exchange system capable of giving rapid and efficient 15 service.

It is a further object of the invention to provide improvement suitable for use in connection with any type of automatic system, whether full-automatic or semi-automatic.

It is also an object of this invention to provide an improved registering and controlling equipment.

An additional object of the invention is 25 the provision of an improved line switch circuit.

A feature of the invention resides in the use of a translator switch, or secondary registering device, and the means of controlling the same. A further feature resides in the method of shifting control successively to the various registering devices.

Added features may be found in the method of associating a register and controlling equipment with a switching link; in the method employed for setting up the class of service registration; and in various other novel circuit arrangements which will be more clearly apparent from the following description and the appended claims.

A still further feature of the invention relates to a method for causing the restoration of the individual line switch in a minimum of time.

Referring to the drawings, Figure 1 shows a circuit of a line switch individual to a calling subscriber; Figure 2 shows a circuit of a district selector switch, and a controlling sequence switch therefor; Figure 3 shows a class and controlling sequence switch and various auxiliary relays; Figure 4 shows a register control switch and one of the register switches; Figure 5 shows

a second register switch and indicates diagrammatically, portions of a translator switch which is positioned under the joint control of the first two registers. The thousands register is also shown in this figure. Figure 6 shows the sender circuit including counting relays and a controlling sequence switch, together with various relays; Figure 7 shows a sequence switch used for sending impulses in case a call is to be extended to a relay call indicator operator's position. Within the dotted square in the lower left-hand portion of this figure are shown contacts controlled by the class sequence switch of Figure 3. Figure 8 shows the remaining register switches; Figure 9 shows the circuits of an office selector switch; Figure 10 shows the arrangement of letters and numerals on a dial suitable for use with a system of the type disclosed in this application; Figure 11 shows more completely the circuits of the translator switch together with a more complete wiring of the contact banks of the first two registers than is shown in Figures 4 and 5; Figure 12 shows the circuits of an incoming selector switch; Figure 13 shows the circuits of a final selector switch; Figure 14 shows the circuits of a monitoring device associated with the sender circuits whereby an operator may observe the progress of operations; and Figure 15 shows the relation to one another in which the various sheets should be placed in order to properly coordinate the various circuits.

It is thought that the invention will best be understood from a detailed description 90 of the operation of the system, reference being had to the accompanying drawings.

When the subscriber at substation 1 removes his receiver from the switchhook, a circuit is completed from grounded battery, 95 winding of line relay 2, inner lower armature and back contact of cut-off relay 3 through the loop of the calling substation line, upper armature and back contact of relay 3 to ground. Line relay 2 is energized 100 in this circuit and attracts its armatures. Since the test brush 5 is in engagement with its normal contact and since its normal contact is connected to ground, the energization of line relay 2 completes a circuit from 105 grounded battery, winding, armature and

back contact of stepping magnet 4, lower armature and back contact of cut-off relay 3, right-hand armature and front contact of the line relay 2, conductor 15, test brush 5, 5 normal terminal 19 to ground. Magnet 4 is energized, and upon energization interrupts its own circuit to release its armature and advance the line switch into its first off-normal position. As soon as the line switch 10 makes its first step, off-normal contact 13 closes and off-normal spring 14 releases its upper contact and engages its lower contact. Off-normal contact 14 removes the control of the cut-off relay from any line which may 15 be calling and supplies battery to test terminal 16 to render the calling line busy to other calling subscribers. The test terminals of trunks extending to busy district circuits will be characterized by the presence of 20 ground potential on such test terminals as will be evident from the following description. As long as test brush 5 engages contacts of busy trunks ground will be supplied to conductor 15 and stepping magnet 4 25 will continue to interrupt its own circuit to cause the advance of the line switch. As soon as test brush 5 engages a terminal on which there is no ground potential the circuit for magnet 4 is opened, and the switch 30 is brought to rest with its brushes on the terminal set of an idle trunk leading to an available district selector.

It should be noted that during the operation of this switch a circuit is in existence 35 for cut-off relay 3 extending from ground, upper and lower windings of cut-off relay 3, left-hand winding of line relay 2, left-hand armature and front contact of relay 2, right-hand armature and front contact of relay 40 2, lowermost armature and back contact of cut-off relay 3 and thence to grounded battery through the winding of magnet 4. Cut-off relay 3 cannot, however, be energized in this circuit since its winding is short-circuited by the direct ground supplied to conductor 15 by way of test terminals 9. As soon as the brush set comes to rest on the selected terminal set, a circuit is completed from grounded battery, resistance 199 (Fig. 45 2), contacts of sequence switch spring 198, armature and back contact of relay 102, conductor 106, terminal 9, test brush 5, conductor 15, left-hand winding, armature and front contact of line relay 2, through the 50 windings of cut-off relay 3 to ground. The presence of battery potential at terminal 9 short-circuits magnets 4 and allows cut-off relay 3 to operate. The operation of cut-off relay 3 causes the deenergization of line 55 relay 2.

A circuit is then completed from grounded battery (Fig. 2), right-hand winding of relay 102, armature and back contact of relay 139, lower right-hand contact of sequence 60 switch spring 103, sleeve conductor 104, terminal 11, brush 7, winding of message register magnet 17, lower middle armature and front contact of relay 3, lower holding winding of relay 3, to ground. Relay 102 is energized and at its inner left-hand armature 70 and front contact supplies ground by way of conductor 105, to test conductor 106 and its associated test contacts, to render this trunk non-selectable to other hunting line switches. The energization of relay 102 75 also completes a circuit from grounded battery, right-hand winding of relay 107, upper left-hand contact of sequence switch spring 108, lower contacts of sequence switch spring 109, right-hand armature and front contact 80 of relay 102 to ground. Relay 107 is energized in this circuit. Assuming that the sender on the terminals of which the brushes of the sender selector are resting is busy and that this busy condition is indicated by the 85 presence of ground on the test terminal of such sender, a locking circuit for relay 107 is completed from grounded battery, left-hand winding and left-hand armature and front contact of relay 107, conductors 110 90 and 111, upper left-hand contact of sequence switch spring 112, lower left-hand contact of sequence switch spring 113, conductor 114, test brush 115 and its associated test terminal, to ground. Relay 107 also completes a 95 circuit from grounded battery, power magnet of sequence switch 100, lower right-hand contact of sequence switch spring 116, inner right-hand armature and front contact of relay 107, lower contact of sequence switch 100, 100 lower right-hand contact of sequence switch spring 117, to ground, for moving this sequence switch out of position 1 and into position 2 under the control of its master spring contact 101.

In position 2 of sequence switch 100 a circuit is completed for causing the selection of an idle sender. The circuit for the sender selector stepping magnet 118 is completed from grounded battery, armature and back contact of magnet 118, winding of 110 magnet 118, conductor 119, lower contact of sequence switch spring 120, inner right-hand armature and front contact of relay 107, and the lower contact of sequence switch spring 117 to ground. Stepping magnet 118 interrupts its own circuit and causes the advance of the sender selector brushes until an idle sender is found. When an idle sender is found the absence of ground on the test terminal of such sender breaks 115 the locking circuit of relay 107 and this relay deenergizes, at the same time opening the circuit of stepping magnet 118 and bringing the sender selector to rest. Relay 107 upon deenergization also completes a 120 circuit from grounded battery, power magnet of sequence switch 100, upper right-hand contact of sequence switch spring 116, inner right-hand armature and back contact of relay 107, lower contact of sequence 125 130

switch spring 103, sleeve conductor 104, ter-

switch spring 117 to ground, for moving this sequence switch out of position 2 and into position 3.

During the hunting movement of the sender selector a circuit is in existence from grounded battery, armature and back contact of stepping magnet 118, winding of magnet 118, winding of relay 121, lower contacts of sequence switch spring 122, inner 10 left-hand armature and front contact of relay 102, to ground. The presence of direct ground on conductor 119 shunts relay 121 at this time to prevent its operation. However, as soon as relay 107 is deenergized this 15 shunt is removed and relay 121 is energized to connect the controlling leads to the selected sender. Relay 121 at its inner left-hand armature supplies ground to the terminal associated with test brush 115 to render the sender non-selectable by other sender 20 selectors.

As soon as the sender has been seized and relay 121 has operated, a circuit is completed from grounded battery, through the 25 winding of relay 202 (Fig. 3), upper left-hand and lower right-hand contacts of sequence switch spring 203, conductors 204, and 205, test brush 115 and its associated contact, conductor 114, inner left-hand armature and front contact of relay 121 to ground. Relay 202 is energized and completes a circuit from ground, outer right-hand armature and back contact of relay 206, outer left-hand armature and front contact of relay 202, outer left-hand armature and back contact of relay 207, conductors 208, and 209, outer right-hand armature and back contact of relay 210, conductors 211 and 302, upper right-hand contact of impulser sequence switch spring 402, winding of power magnet 400 of the impulser sequence switch, to grounded battery. Power magnet 400 is energized in this circuit and advances the impulser sequence switch out 40 of position 1 and into position 13 under the control of the master spring 401. The purpose of the movement of the impulser sequence switch at this time is to provide the same time interval necessary before dialing 45 tone is supplied, in case the subscriber is connected to the district by means of a line switch instead of by a line finder. When sequence switch 400 reaches position 5, a circuit is completed from grounded battery, 50 winding of relay 207, conductors 212 and 303, upper left-hand contact of sequence switch spring 403 to ground. It is, of course, obvious that the time which expires before relay 207 is energized, may be controlled by varying the cutting of sequence switch spring 403 so that a greater or less time will be consumed before relay 207 is energized. Relay 207 upon energization, locks up through its outer right-hand armature and front contact to grounded conductor

205, and at the same time connects through the calling subscriber's line to the sender, incidentally supplying him with a dial tone to inform him that he is free to dial. Relay 207 upon energization also 70 completes a circuit from grounded battery, winding of sequence switch magnet 200, upper right-hand contact of sequence switch spring 219, outer left-hand armature and front contact of relay 207, left-hand armature and front contact of relay 202, outer right-hand armature and back contact of relay 206, to ground for moving this sequence switch out of position 1 and into 75 position 3, under the control of its master sequence switch 201.

The primary circuit of the induction coil by means of which the dialing tone is supplied to the calling subscriber extends from a suitable source of tone through the left-hand winding of induction coil 213, conductor 214, register brush 500 in its normal position, conductor 501, outer left-hand armature and back contact of relay 502, to ground at the right-hand armature and back 90 contact of slow-to-release relay 503. The current in this circuit is induced into the receiver of the calling subscriber's substation set over a circuit extending from grounded battery, winding of line relay 215, 95 conductor 616, inner left-hand armature and back contact of relay 600, conductor 601, inner right-hand armature and front contact of relay 207, conductor 216, sender selector brush 123 and its associated contact, outer 100 left-hand armature and front contact of relay 121, conductor 124, upper left-hand contact of sequence switch spring 125, conductor 126, through the contact of the line switch to the calling subscriber's station, through 105 the tip contacts of the line switch, conductor 127, upper left-hand contact of sequence switch spring 128, conductor 129, sender selector brush 130, and its associated contact, conductor 131, inner left-hand armature and front contact of relay 207, conductor 617, right-hand armature and back contact of relay 600, conductor 602, right-hand winding of induction coil 213 to ground. When the calling subscriber hears this dialing tone he 110 operates his sub-station dial to send out series of impulses to the set of registers in the 115 selected sender.

It will be assumed that the line to be selected is one which terminates in a full mechanical exchange, which may be selected directly by means of a district selector and an office selector. In this case the registers and class register will have to be set in such a position as to control brush and group selection at the district office, and incoming switches, and brush, group, and line selection at the final switch.

It has been found in practice that when it is necessary for a subscriber to remember 130

a number of more than four digits, confusion is apt to result. However, if an office name is used in connection with four digits, he can readily remember this. It is, therefore, 5 proposed to provide the subscriber with a dial in which each digit has an accompanying letter or letters. If then the subscriber is instructed to dial the first two letters of the desired exchange name and then the digits 10 of the wanted line in the exchange, the desired size of installation and range of connections may be accomplished without causing any confusion to the subscriber. Assuming that the wanted line is Grand 5678, 15 an inspection of Fig. 10 will show that the subscriber will first insert his finger in the hole containing the letter G and the digit 3 to send four impulses. He will then operate his dial to send the letter R or 8 impulses 20 after which he will send series of 6, 7, 8 and 9 impulses respectively.

In order to more fully understand the operation of the above mentioned dial, it will be necessary to refer to Fig. 10 of the 25 drawing. It will be noted that the zero of this dial is in the position usually allotted to numeral 1. This change was made as it was necessary in the operation of applicant's sender to register one impulse for 30 the digit zero. For this reason, one extra impulse is set out for each succeeding numeral such as four impulses for No. 3 and ten impulses for No. 9.

In order to prevent confusion as to which 35 switches the various brushes and contact arcs shown in Figs. 4, 5 and 8 are related the brushes belonging to the progression switch or side switch have been indicated by the letters SS; the arms belonging to the register 40 which is set in response to the first series of impulses of the office code have been designated by the letter A; the arms belonging to the register which is operated in response to the second series of impulses of the office 45 code have been designated by the letter B; the brushes of the thousands register are identified by the letters TH; and those of the hundreds, tens, and units register have been designated by the letters H, T, and U, 50 respectively. The three registers shown at the right in Fig. 8, have not been described. These registers are provided in order to allow a calling subscriber to dial the digits of a wanted station in a P. B. X. exchange. 55 Since they are not brought into use in the ordinary operation of the system and since they are not necessary to an understanding of the various features of the invention, their operation has not been described.

60 The various contact controlled by sequence switch 400 (Fig. 7) are used to control indicating lamps at a relay call indicator operator's position. It was necessary to show sequence switch 400 since it is used for measuring a time interval, but since the opera-

tion of relay call indicators is well-known in the art, it has not been considered necessary to describe the complete operation of the impulse switch in case a call is extended to a relay call indicating position. 70

Relay 215 is energized upon the completion of the above traced dial tone circuit and causes in turn the energization of slow-to-release relay 217, which in turn causes the energization of relay 218. The first 75 interruption due to the operation of the calling subscriber's dial, causes the deenergization of relay 215. This interruption being of short duration, however, relay 217 holds over, thereby maintaining relay 218 80 also in energized condition. Upon the deenergization of relay 215 a circuit is completed from grounded battery, resistance 504, winding of relay 503, conductor 523, winding of magnet 505, which controls the 85 advance of the A register, conductor 506, side switch brush 507 and its normal contact, conductor 508, inner left-hand armature and front contact of relay 218, armature and back contact of relay 215, to 90 ground. Stepping magnet 505 is energized to cause the register to advance one step. Relay 503 is energized and being slow to release, remains energized until the completion of the series of impulses. In response to the first series of impulses the relay 215 is deenergized 4 times and upon each deenergization causes the stepping magnet 505 to advance the register brushes 95 one step. Upon completion of the series of impulses, the A register will be in its third off-normal position. 100

At the termination of the series of impulses, relay 215 maintains its armature attracted for a relatively long period of time 105 with the result that relay 503 is deenergized. Upon the deenergization of relay 503 a circuit is completed from ground at the right-hand armature and back contact of relay 503, through the winding of relay 110 519, conductor 509, upper left-hand and lower right-hand contact of sequence switch spring 220, conductor 221, through the station register brush 511 and its normal contact, and thence through brushes 512, 513, 514, 515, 516 and the respective 115 normal contacts of the units, tens, hundreds, thousands and B registers respectively, thence through brush 517 of the A register, which, due to the fact that this register has 120 been positioned, is in some off-normal position, conductor 518, armature and back contact of magnet 505, windings of magnet 505 and relay 503 to battery. Relay 503 and magnet 505 do not energize in series 125 with relay 519. Relay 519 is energized in this circuit and completes a circuit from grounded battery, winding of side switch stepping magnet 520, and armature and back contact of magnet 520, conductor 521, 130

left-hand armature and back contact of relay 503, side switch brush 522 and its normal contact, left-hand armature and front contact of relay 519 to ground. Magnet 520 is energized and moves the side switch out of its normal position and into position 1.

It should be observed that the side-switch, which comprises brushes 507, 522, 586 and 581, is preferably of the same mechanical construction as the register switches. The preferred form of mechanism is similar to that shown and described in the patent to O. F. Forsberg and R. M. De Vignier, 1,472,465, issued October 30, 1923.

The calling subscriber now sends the second series of impulses in order to position the B register. The first interruption of the line circuit will cause the deenergization of line relay 215, whereupon a circuit is completed from grounded battery, resistance 504, winding of slow release relay 503, conductors 523 and 524, winding of stepping magnet 525 which controls the B register, conductor 526, side-switch arm 507 which is in contact with its first off-normal terminal, conductor 508, inner left-hand armature and front contact of relay 218, armature and back contact of relay 215 to ground. Stepping magnet 525 and relay 503 are energized in this circuit. Relay 503 being slow to release retains its armature attracted until the completion of the series of impulses. Upon the next closure of the line circuit, line relay 215 attracts its armature and magnet 525 releases to advance the B register one step. At the conclusion of the sending of the second series of impulses, the B register will be in position 8. At the conclusion of the series of impulses, line relay 215 remains energized for a relatively long period of time with the result that relay 503 becomes deenergized. The deenergization of relay 503 completes a circuit from grounded battery, winding of side-switch stepping magnet 520, armature and back contact of magnet 520, conductor 521, left-hand armature and back contact of relay 503, side-switch brush 522 in its first position, conductor 527, brush 528 of the B register, which is now in an off-normal position, to ground. Magnet 520 is energized and interrupts its own circuit to cause the advance of the side-switch into position 2.

In position 2 of the side switch, the impulse circuit is diverted to stepping magnet 529 of the thousands register by way of side-switch brush 507 and its second contact and conductor 530. Relay 503 and stepping magnet 529 are energized in series and relay 503 remains energized during the sending of the series of impulses while stepping magnet 529 causes the advance of the thousands register into position 6.

Upon the completion of the sending of the thousands impulses, the side switch is advanced into position 3 over a circuit extending from grounded battery, winding of stepping magnet 520, armature and back contact of magnet 520, conductor 521, left-hand armature and back contact of relay 503, side switch brush 522 and its second contact, thence by way of conductor 531 to the thousands register brush 532, which is now in an off-normal position, to ground. The completion of this circuit advances the side switch into position 3.

The setting of the hundreds, tens and units registers is accomplished in substantially the manner described, since stepping magnets 533, 534 and 535 are successively brought under the control of line relay 215 as the side switch arm 507 advances from position to position. Upon completing the setting of the registers, the side switch arms will be in contact with their No. 5 terminals.

As soon as the A and B registers have been positioned, at which time the side switch will be in position 2, a circuit is completed from grounded battery, winding of relay 502, side switch arm 586 and its associated contact, conductor 537, right-hand armature and front contact of relay 218 to ground. Relay 502 is energized and completes a locking circuit for itself extending from its inner right-hand armature and front contact to conductor 538, conductor 273, upper left-hand contact of sequence switch spring 274, to ground.

The setting of the translator switch will now be described. The translator switch has two sets of brushes, which are herein designated generally as T¹ and T². After being set into motion, the translator will hunt for a position controlled by the joint setting of the A and B registers.

The translator switch is of such simple construction that it has not been necessary to provide a drawing of its mechanism. Two arcuate contact banks, each comprising a number of contact sets and each contact set comprising a plurality of contacts, are arranged side by side and supported by a suitable frame. A brush shaft carrying two brush sets arranged to cooperate with the contact sets, is mounted in operative relation to the contact banks in the same frame. The brush sets are 180° apart in rotation, that is, they are diametrically opposite one another on the shaft, and the arrangement is such that when one brush set completes its travel over its associated contact bank, the other brush set will begin its travel over its associated contact bank. Power is transmitted to the shaft from a constantly rotating shaft by means of clutch discs magnetically controlled in the manner commonly employed in the construction of sequence

switches. The power source is indicated in the present disclosure by magnet 540. Since the brushes are driven at high speed, a stop magnet, represented in the drawings by magnet 541, has been provided in order to insure their stopping on the desired terminal set.

As soon as relay 502 is energized, a circuit is completed from grounded battery, 10 resistance 542, right-hand armature and back contact of relay 543, conductor 544, winding of power magnet 540, conductor 545, inner left-hand armature and front contact of relay 502 to ground. Power magnet 540 is energized and starts the translator switch into operation. In order to prevent needless confusion of the drawings, the complete interconnections of the various contact arcs of the A and B registers have 20 not been shown in Figs. 4 and 5. In order to obtain a more complete understanding of the circuits which determine the positioning of the translator, reference may be had to Fig. 11 which shows the interconnections 25 more completely.

Referring then to Fig. 11, it will be seen that the translator, after being put in motion, will continue to revolve until test brush 546, which serves the bank designated at 30 T^2 reaches contact No. 12, at which time a circuit will be completed from grounded battery, right-hand armature and back contacts of relay 543, low resistance left-hand winding of relay 543, conductor 547, A register brush 548 and contact No. 3, conductor 549, B register brush 550 and its associated terminal No. 7, conductor 551, the No. 12 contact in the arc served by brush 546, conductors 552 and 545 to ground at the armature and front contact of relay 502. The low resistance of the left-hand winding of relay 543 shunts down the power magnet and brings the translator switch to rest.

During the hunting operation of this 45 switch a circuit was in existence for stop magnet 541, this circuit extending from grounded battery, winding of magnet 541, conductor 547, low resistance left-hand winding of relay 543, conductor 544, outer 50 right-hand armature and back contact of relay 543, winding of power magnet 540 to ground at the armature and front contact of relay 502. The current flowing in this circuit is not sufficient to allow magnet 541 55 to become energized, but it does set up enough magnetism so as to allow stop magnet 541 to act very quickly when the proper terminal set is found. When the proper terminal is found, stop magnet 541 is energized due to the completion of a circuit for magnet 541 in parallel with that just traced for the left-hand winding of relay 543. Magnet 541 is now fully energized and relay 543 is sufficiently energized to attract its 60 armature, thus breaking the driving circuit.

of power magnet 540 and causing relay 543 to include both its right and left-hand windings in a holding circuit.

Referring now to Fig. 3, it will be observed that as soon as relay 543 becomes 70 energized a circuit is completed from grounded battery, power magnet of sequence switch 200, lower left-hand contact of sequence switch spring 219, left-hand armature and back contact of relay 223, conductor 227, outer left-hand armature and front contact of relay 543 to ground for moving this sequence switch out of position 3 and into a position determined by the setting of the translator switch. The sequence 80 switch 200 is the sequence switch which determines the class and routing of the call and in accordance with its setting will be determined the number and kind of impulses to be sent, that is, whether office impulses will be sent, whether relay call indicator impulses will be sent, whether the call will be directed to a special operator, or any of the various combinations essential 85 in a large installation. 90

The extent of motion of sequence switch 200 will be determined by the point in its operation at which relay 223 is energized. Relay 223 has its circuit successively extended to conductors 228, 229, 230, 231, 232, 233, 234, 235 and 236 as the sequence switch moves through its various positions. These conductors extend to various terminals in the contact banks of the translator. To avoid complexity of the circuits, these leads 100 have not been carried down to the translator bank terminals, a single conductor 553 being utilized to indicate the manner in which these contacts will be connected to the arc of contacts which controls the positioning of the class register. 105

Since it has been assumed that the call is to be an interoffice, full mechanical call, the class register, that is the sequence switch 200, will be brought to rest in position 7. 110 To accomplish this, lead 229 would have to be wired to the No. 12 terminal in the class arc of the contact bank served by the T^2 brush set of the translator. If we assume this to be the case, then when sequence switch 200 reaches position $6\frac{3}{4}$, a circuit is completed from grounded battery, winding of relay 223, upper left-hand and lower right-hand contacts of sequence switch spring 237, conductor 229, brush 554, conductor 555, inner left-hand armature and front contact of relay 543 to ground. Relay 223 is energized in this circuit and locks up through its inner-right-hand armature and front contact and the lower contact of sequence switch spring 238 to ground. The energization of relay 223 opens the driving circuit of sequence switch 200 and brings this switch to rest in position 7. 125

The energization of relay 223 also com- 130

- plete a circuit from grounded battery, power magnet of sequence switch 300, Fig. 6, the upper right-hand contact of sequence switch spring 313, conductors 314 and 315, 5 left-hand armature and front contact of relay 223, conductor 227, outer left-hand armature and front contact of relay 543 to ground, for moving this sequence switch out of position 1 and into position 2.
- 10 As soon as sequence switch 300 reaches position 2 a circuit is completed from grounded battery, left-hand winding of relay 107, lower left-hand and upper right-hand contacts of spring 112, inner right-hand armature and front contact of relay 121, sender selector brush 132 and its associated contact, conductor 133, outer right-hand armature and back contact of relay 239, upper right-hand contact of sequence 15 switch spring 240, conductors 241 and 316, inner right-hand armature and back contact of relay 317, lower right-hand contact of sequence switch spring 318, winding of stepping relay 320, armature and back contact of relay 321, which is connected in parallel with the 0' counting relay, inner left-hand armature and back contact of relay 306, resistance 322, upper left-hand contact of sequence switch spring 312, to ground. Relays 107 and 320 are energized in this circuit.
- The energization of relay 107 completes a circuit from grounded battery, power magnet of sequence switch 100, lower right-hand contact of sequence switch spring 116, inner right-hand armature and front contact of relay 107, lower contact of sequence switch spring 117, to ground, for moving sequence switch 100 out of position 3 and into position 4. Relay 107 remains energized in position 4 of sequence switch 100, due to the closure of a locking circuit extending from grounded battery, left-hand winding of relay 107, left-hand armature and front contact of relay 107, conductors 110 and 111, upper left-hand contact of sequence switch spring 112, to ground over the path described.
- In position 4 of the sequence switch a circuit is completed for up-drive magnet 134. This circuit extends from grounded battery, winding of magnet 134, upper right-hand contact of sequence switch spring 120, inner right-hand armature and front contact of relay 107, lower contact of sequence switch spring 117 to ground. The energization of magnet 134 causes the district selector to advance its brush shaft in a brush selecting movement.
- 55 Referring now to Fig. 6, it will be observed that the energization of stepping relay 320 completes a circuit from ground, upper right-hand contact of sequence switch spring 312, armature and front contact of relay 320, upper left-hand contact of sequence switch spring 309, outer left-hand armature and back contact of relay 308, outer left-hand armature and back contact of relay 307, inner right-hand armature and back contact of relay 306, conductor 305, 75 lower right-hand contact of sequence switch spring 304, upper left-hand contact of sequence switch spring 323, lower right-hand contact of sequence switch spring 409 (which it will be remembered, is controlled by the class register switch shown in Fig. 3, and is therefore closed in position 7), conductor 410, translator brush 556, which is in engagement with the twelfth terminal of the T² contact bank, and thence through the 80 winding of one of the counting relays to grounded battery.
- In order to simplify the disclosure, the wiring of the counting relays to the various contact sets in the translator bank has not been shown. It will be assumed, however, that with the translator set with one of its brush sets in engagement with the twelfth terminal set in the T² contact bank, the third brush set and the fourth group served thereby will be selected at the district switch. It will further be assumed that with the same setting the second brush set and the third group served thereby will be selected by the office selector switch.
- Under the assumption made, contact No. 12 in the arc served by brush 556 will be connected to the No. 2 counting relay; contact No. 12 served by brush 557 will be connected to the No. 3 counting relay; contact No. 12 served by brush 558 will be connected to the No. 1 counting relay and contact No. 12 in the arc served by brush 559 will be connected to the No. 2 counting relay.
- Bearing these assumptions in mind, the 105 circuit which is completed upon the energization of stepping relay 320 will then extend from brush 556 to the winding of the No. 2 counting relay, Fig. 6, to grounded battery. The No. 2 counting relay is energized in this circuit and prepares, in the well-known manner, a circuit for the No. 2' counting relay by way of conductor 324, lower right-hand contact of sequence switch spring 325, conductors 326 and 327, to ground, at sequence switch spring 312. The winding of the No. 2' counting relay is, however, shunted by the ground controlled at the armature and front contact of relay 320 and does not energize at this time.
- 110 As soon as the district brush has advanced a sufficient distance to allow the commutator brush 135 to engage the first conducting segment of commutator 136, stepping relay 320 is shunted down, since the locking circuit of relay 107 now extends from grounded battery, left-hand winding of relay 107, left-hand armature and front contact of relay 107, conductors 110 and 111, upper left-hand contact of sequence 115
- 120
- 125
- 130
- 135

switch spring 112, upper right-hand contact of sequence switch spring 113, commutator 136, commutator brush 135, to ground. The shunting of stepping relay 320 causes it to deenergize and remove the shunt from the No. 2' counting relay, which relay becomes energized and prepares a circuit for the No. 1 counting relay in the well-known manner. Only a portion of the counting relays have been shown, but since the operation of counting relays is well known in the art, it is thought that the disclosure will be sufficient to indicate the method of their operation. When brush 135 leaves the conducting segment of commutator 136, the shunt is removed from stepping relay 320 and this relay again energizes, causing the energization of counting relay No. 1. Counting relay No. 1 prepares a circuit for the No. 1' counting relay.

The third shunting down of the stepping relay will allow the energization of the 0' counting relay and relay 321 in parallel, this circuit extending to ground by way of the armature and front contact of No. 0 counting relay, conductor 324, lower right-hand contact of sequence switch spring 325, conductors 326 and 327, to ground at sequence switch spring 312. The energization of the 0' counting relay completes a circuit from grounded battery, winding of power magnet of sequence switch 300, lower right-hand contact of sequence switch spring 331, conductor 340, left-hand armature and back contact of relay 332, conductor 334, inner right-hand armature and back contact of relay 307, armature and front contact of the 0' counting relay, to ground for moving this sequence switch out of position 2 and into position 4.

The energization of relay 321 opens the lower branch of the locking circuit of relay 107 and when, a moment later, brush 135 engages an insulating segment of commutator 136, the circuit of relay 107 is broken and this relay deenergizes, completing a circuit from grounded battery, power magnet of sequence switch 100, upper right-hand contact of sequence switch spring 116, inner right-hand armature and back contact of relay 107, lower contact of sequence switch spring 117 to ground for moving sequence switch 100 out of position 4 and into position 5. The deenergization of relay 107 also opens the circuit of updrive magnet 134 and brings the selector to rest in a position to trip the third set of brushes.

As soon as sequence switch 300 leaves position 2, the locking circuits of the counting relays are broken at the upper and lower right-hand contacts of sequence switch spring 325, and the counting relays are restored.

In position 5 of sequence switch 100 the fundamental circuit is again completed, this

circuit extending from grounded battery, left-hand winding of line relay 107, lower left-hand and upper right-hand contacts of sequence switch spring 112, inner right-hand armature and front contact of relay 121, brush 132 and its associated contact, conductor 133, outer right-hand armature and back contact of relay 239, upper right-hand contact of sequence switch spring 240, conductors 241 and 316, inner right-hand armature and back contact of relay 317, lower right-hand contact of sequence switch spring 318, winding of stepping magnet 320, armature and back contact of relay 321, inner left-hand armature and back contact of relay 306, resistance 322, upper left-hand contact of sequence switch spring 312 to ground. Relays 107 and 320 are energized in this circuit, relay 107 completing a locking circuit for itself by way of its left-hand armature and front contact, conductors 110 and 111, and the upper left-hand contact of sequence switch spring 112 to ground over the path described. Relay 107 also completes a circuit from grounded battery, power magnet of sequence switch 100, lower right-hand contact of sequence switch spring 116, inner right-hand armature and front contact of relay 107, lower contact of sequence switch spring 117 to ground for moving sequence switch 100 out of position 5 and into position 6.

In position 5 of sequence switch 100 a circuit was completed from grounded battery, winding of trip magnet 137, upper right-hand and lower left-hand contacts of sequence switch spring 122, inner left-hand armature and front contact of relay 102, to ground. The trip magnet was energized in this circuit to operate the trip rod so that on subsequent upward movement of the brush rod the third set of brushes will be released into engagement with the contact bank served by it.

The above mentioned energization of stepping relay 320 completes a circuit for the No. 3 counting relay, extending from grounded battery, winding of the No. 3 counting relay (not shown), the armature and back contact of the No. 3' counting relay, the No. 12 terminal in the arc served by brush 557, conductor 560, lower right-hand contact of sequence switch spring 411, conductor 412, upper right-hand contact of sequence switch spring 323, lower right-hand contact of sequence switch spring 304, conductor 305, inner right-hand armature and back contact of relay 306, outer left-hand armature and back contact of relay 307, outer left-hand armature and back contact of relay 308, lower contact of sequence switch spring 309, armature and front contact of stepping relay 320, conductors 310 and 311, lower contact of sequence switch spring 312, to ground.

The No. 3 counting relay is energized and prepares a circuit for the No. 3' counting relay.

In position 6 of sequence switch 100 a circuit is again completed for up-drive magnet 134, extending from grounded battery, winding of magnet 134, upper right-hand contact of sequence switch spring 120, inner right-hand armature and front contact 10 of relay 107, lower contact of sequence switch spring 117 to ground. Under the control of magnet 134, the selector brush shaft is moved upwardly to select the desired group. As soon as commutator brush 194 engages a conducting portion of commutator 138, stepping relay 320 is shunted down and deenergizes to allow the energization of counting relay No. 3'.

On the fourth shunting down of stepping relay 320, counting relay 0' in parallel with relay 321, is energized as previously described. The energization of relay 321 opens the lower branch of the locking circuit of relay 107 and when a moment 25 later brush 137 engages an insulating segment of commutator 138, the locking circuit of relay 107 is broken and this relay deenergizes. The deenergization of relay 107 completes a circuit from grounded battery, power magnet of sequence switch 100, upper right-hand contact of sequence switch spring 116, inner right-hand armature and back contact of relay 107, lower contact 30 of sequence switch spring 117, to ground, for moving sequence switch 100 out of position 6 and into position 7. The deenergization of relay 107 also opens the circuit of up-drive magnet 134 and brings the selector to rest.

40 With sequence switch 100 in position 7, a circuit is completed from grounded battery, right-hand winding of relay 107, upper left-hand contact of sequence switch spring 108, lower contacts of sequence switch spring 45 109, right-hand armature and front contact of relay 102 to ground. Relay 107 is energized in this circuit.

It is to be observed at this point that when sequence switch 100 reached position 3, 50 a circuit was completed from grounded battery, right-hand winding of relay 139, upper left-hand contact of sequence switch spring 140, conductor 141, outer right-hand armature and front contact of relay 121, 55 lower right-hand contact of sequence switch spring 142, sender selector brush 143, and its associated contact, conductor 144, outer left-hand armature and back contact of relay 239, conductor 242, resistance 243, conductor 244, upper left-hand contact of sequence switch spring 341, conductors 326 and 327, to ground at sequence switch contact 312. Relay 139 was energized in this circuit and at its left-hand armature transferred the holding circuit of relay 102 from

the lower right-hand contact of sequence switch spring 103 to the upper right-hand contact of sequence switch spring 103. Relay 139 remains energized until sequence switch 100 leaves position 10 except in the case of an abandoned call, which condition will be described hereinafter.

With relays 107 and 139 energized in position 7 of sequence switch 100, a circuit is completed from grounded battery, power magnet of sequence switch 100, lower right-hand contact of sequence switch spring 116, inner right-hand armature and front contact of relay 107, right-hand contact of sequence switch spring 117, right-hand armature and front contact of relay 139 to ground, for moving sequence switch 100 out of position 7 and into position 8. As soon as sequence switch 100 reaches position 7½ 75 a locking circuit for relay 107 is completed, extending from grounded battery, left-hand winding of relay 107, left-hand armature and front contact of relay 107, conductor 110, lower left-hand and upper right-hand contacts of sequence switch spring 145, to test brush 146 and its associated contact and thence to ground, providing the associated trunk is busy. It will be assumed that the first trunk in the group is busy. Relay 107, therefore, remains energized and completes a circuit from grounded battery, winding of up-drive magnet 134, upper right-hand contact of sequence switch spring 120, inner right-hand armature and front contact of relay 107, lower contact 80 of sequence switch spring 117, to ground. The selector brush set is now moved upwardly over the terminals in the selected group and when an idle trunk is encountered, ground will no longer be found on the terminal associated with test brush 146. This branch of the locking circuit of relay 107 is, therefore, broken but the relay is held energized an instant longer in order to properly center the brush set due to the closure of a circuit extending from grounded battery, right-hand winding of relay 107, upper right-hand contact of sequence switch spring 108, a conducting portion of commutator 149, commutator brush 180, to ground. As soon as commutator brush 180 engages an insulating segment of commutator 149, at which time the brushes will be accurately centered on the selected terminal set, all branches of the locking circuits of relay 107 are opened and this relay deenergizes, causing in turn the deenergization of up-drive magnet 134 and bringing the selector to rest. The district selector has now been actuated to seize a trunk leading to an idle office selector switch.

The deenergization of relay 107 also completes a circuit from grounded battery, power magnet of sequence switch 100, upper right-hand contact of sequence switch

spring 116, inner right-hand armature and back contact of relay 107, lower contact of sequence switch spring 117, to ground, for moving this sequence switch out of position 5 and into position 9.

- During brush and group selection and during trunk hunting at the district switch, the relay 210, Fig. 3, is maintained energized over a circuit extending from grounded battery, winding of relay 210, conductor 245, lower contact of sequence switch spring 342, outer left-hand armature and back contact of relay 306, conductor 343, sender selector brush 150 and its associated contact, right-hand contacts of sequence switch spring 151 to ground. The function of relay 210 is to prevent the advance of the sender controlling sequence switch until trunk hunting has been completed at the district switch.
- As soon as sequence switch 100 leaves position 8, relay 210 is deenergized whereupon a circuit is completed from grounded battery, power magnet of sequence switch 300, conductors 336 and 337, outer left-hand armature and back contact of relay 210, conductor 338, upper right-hand and lower left-hand contacts of sequence switch spring 339, conductor 340, left-hand armature and back contact of relay 332, conductor 334, inner right-hand armature and back contact of relay 307, to ground at the armature and front contact of the 0' counting relay. The completion of this circuit moves sequence switch 300 out of position 4 and into position 6.

The operation just described is that which takes place in case an office selector switch is to be operated. In case the office is to be selected directly by the district switch, circuits will become effective to advance sequence switch 300 out of position 4 directly into position 9. This would be accomplished in the following manner: The translator switch shown in Fig. 5 would now occupy a different setting which would be a setting such that brush 558 would be in engagement with a terminal connected to conductor 599. In this case sequence switch 300 is moved out of position 4 by means of the same circuits just described. When it reaches position 4 1/4 a circuit is completed from grounded battery, winding of relay 246, conductor 247, upper right-hand contact of sequence switch spring 304, lower right-hand contact of sequence switch spring 323, conductor 248, brush 558, and its associated contact, conductor 599, to ground, at the armature and back contact of relay 332. Relay 246 is energized in this circuit and locks up through its inner right-hand armature and front contact by way of the lower left-hand contact of sequence switch spring 325 and conductors 326 and 327 to ground. When sequence switch 300 reaches position 6, due to the energized condition of relay

246, a circuit is completed from grounded battery, winding of the 0 counting relay, windings of the 0' counting relay and relay 321 in parallel, conductor 344, upper right-hand contact of sequence switch spring 345, 70 outer left-hand armature and front contact of relay 246, conductors 346 and 347, and the upper right-hand contact of sequence switch spring 238 to ground. The 0 and 0' counting relays and relay 321 are energized 75 in this circuit. Relay 321 prevents the closure of the fundamental circuit during this time and the 0' counting relay completes a circuit from grounded battery, winding of the power magnet of sequence 80 switch 300, lower right-hand contact of sequence switch spring 331, conductor 340, left-hand armature and back contact of relay 332, conductor 334, inner right-hand armature and back contact of relay 307, armature and front contact of the 0' counting relay to ground for moving the sequence switch through positions 6 and 8 and into position 9. It is, therefore, obvious that in this case no office impulses will be sent. When the sequence switch leaves position 8, relay 246 is deenergized as are the 0 and 0' counting relays and relay 321.

Under the assumptions made in connection with the present type of call, an office selector is to be operated and, therefore, the sequence switch 300 will stop in position 6 as previously described. When sequence switch 300 leaves position 4, the locking circuits of the counting relays are broken and these relays deenergize.

When sequence switch 100 reached position 4, and sequence switch 300 reached position 4, a circuit was completed from grounded battery, winding of charge relay 152, lower left-hand contact of sequence switch spring 140, conductor 141, outer right-hand armature and front contact of relay 121, lower right-hand contact of sequence switch spring 142, brush 143 and its associated contact, conductor 144, outer left-hand armature and back contact of relay 239, conductor 242, resistance 243, conductor 244, upper left-hand contact of sequence switch spring 341, conductors 326 and 327 to ground. Relay 152 was energized in this circuit and remains energized until sequence switch 100 leaves position 10.

As soon, therefore, as sequence switch 100 reaches position 9, a circuit is completed from grounded battery, right-hand winding of relay 107, upper left-hand contact of sequence switch spring 108, lower right-hand and upper left-hand contacts of sequence switch spring 109, right-hand armature and front contact of relay 152 to ground. Relay 107 is energized and completes a circuit from grounded battery, power magnet of sequence switch 100, lower left-hand contact of sequence switch spring 116, inner right-

hand armature and front contact of relay 107, lower contact of sequence switch spring 117 to ground, for moving sequence switch 100 out of position 9 and into position 10.

5 In position 10, relay 107 remains energized over the circuit previously described.

The fundamental circuit is now extended to the office selector switch shown in Fig. 9. It is to be observed that the trunk leading 10 to the selected office selector switch is made busy against other hunting district selector switches as soon as sequence switch 100 reaches position 8½. Ground is now supplied to test terminal 193 by way of the 15 upper contacts of sequence switch spring 145.

Referring now to Fig. 9 a circuit is completed as soon as sequence switch 100 reaches position 10, this circuit extending from 20 grounded battery, right-hand winding of line relay 702, right-hand contacts of sequence switch spring 703, conductor 710, conductor 704, terminal 153, brush 154, lower right-hand and upper left-hand contacts of 25 sequence switch spring 155, conductor 156, inner right-hand armature and front contact of relay 121, sender selector brush 132 and its associated contact, conductor 133, outer right-hand armature and back contact 30 of relay 239, upper right-hand contact of sequence switch spring 240, conductors 241 and 316, inner right-hand armature and back contact of relay 317, lower right-hand contact of sequence switch spring 318, winding 35 of stepping magnet 320, armature and back contact of relay 321, inner left-hand armature and back contact of relay 306, resistance 322, lower contacts of sequence switch spring 348, conductor 343, sender selector brush 40 150, and its associated contact, lower contacts of sequence switch spring 151, brush 157, terminal 158, conductor 159, left-hand contacts of sequence switch spring 735, to ground. It is to be observed that the 45 stepping relay 320 is now included in a full metallic circuit leading to the office selector switch. Relays 320 and 702 are energized in the above-traced circuit, relay 320 completing a circuit from grounded battery, 50 winding of the No. 1 counting relay, armature and back contact of the No. 1' counting relay, No. 12 terminal served by brush 558 of the translator, conductor 248, lower right-hand contact of sequence switch spring 323, lower right-hand contact of sequence switch 55 304, conductor 305, inner right-hand armature and back contact of relay 306, outer left-hand armature and back contact of relay 307, outer left-hand armature and 60 back contact of relay 308, upper left-hand contact of sequence switch spring 309, armature and front contact of relay 320, upper right-hand contact of sequence switch 312, to ground. The No. 1 counting relay is energized in this circuit and prepares a cir-

cuit for the No. 1' counting relay in the well-known manner.

At the office selector, the energization of relay 702 completes a circuit from grounded battery, power magnet of sequence switch 700, upper left-hand contact of sequence switch spring 705, left-hand armature and front contact of relay 702 to ground, for moving sequence switch 700 out of position 1 and into position 2. 75

In position 2 of sequence switch 700, relay 702 remains energized due to the closure of a locking circuit through its right-hand winding and inner right-hand armature and front contact, upper left-hand contact of sequence switch spring 706 to ground over the fundamental circuit previously described. 80

In position 2 of sequence switch 700 the brush shaft is moved upward to accomplish brush selection under the control of up-drive magnet 707. The circuit of this magnet extends from grounded battery, winding of magnet 707, lower left-hand contact of sequence switch spring 705, left-hand armature and front contact of relay 702 to ground. 90

As soon as commutator brush 708 engages a conducting portion of commutator 709, stepping relay 320 is shunted down, and the locking circuit of relay 702 is maintained by way of conductor 710 and the upper left-hand contact of sequence switch spring 703, commutator 709, commutator brush 708, to ground. The shunting down of stepping relay 320 allows the No. 1' counting relay 95 to be energized. After the switch has made

two steps, at which time the second brush set will be in proper position to be tripped, the 0' counting relay is energized in parallel with relay 321. Relay 321 opens the lower branch of the locking circuit of relay 702 100 and when, a moment later, brush 708 engages an insulating segment of commutator 709, at which time the brush shaft will be properly positioned, relay 702 deenergizes and completes a circuit from grounded battery, power magnet of sequence switch 700, lower left-hand contact of sequence switch spring 711, left-hand armature and back contact of relay 702 to ground, for moving sequence switch 700 out of position 2 and into position 3. 105

The energization of the 0' counting relay completes a circuit from grounded battery, power magnet of sequence switch 300, lower right-hand contact of sequence switch spring 331, left-hand armature and back contact of relay 332, conductor 334, inner right-hand armature and back contact of relay 307, to ground at the armature and front contact of the 0' counting relay. The completion of this circuit moves sequence switch 300 out of position 6 and into position 8. As soon as the sequence switch leaves position 6 the locking circuits of the counting relays are 110 broken and these relays deenergize. 125

In position 3 of sequence switch 700 a circuit is completed from grounded battery, winding of trip magnet 712, upper right-hand contact of sequence switch spring 713 5 to ground. The trip magnet is energized and operates the trip rod so that upon subsequent upward movement of the brush shaft, the second set of brushes will be tripped.

10 As soon as sequence switch 300 reaches position 8 the fundamental circuit is again completed, from grounded battery, right-hand winding of relay 702, right-hand contacts of sequence switch spring 703, conductors 710 and 704, thence over the fundamental circuit previously described, returning by way of conductor 159 and the left-hand contacts of sequence switch spring 735 to ground. Relay 702 is energized and locks 15 20 up through its inner right-hand armature and front contact as before and at its left-hand armature and front contact completes a circuit from grounded battery, power magnet of sequence switch 700, upper left-hand contact of sequence switch spring 705, left-hand armature and front contact of relay 702 to ground, for moving sequence switch 700 out of position 3 and into position 4.

The completion of the fundamental circuit just described above also causes the energization of stepping relay 320, which upon energization, completes a circuit from grounded battery, winding of the No. 2 counting relay, left-hand armature and back contact of the No. 2' counting relay, the No. 12 terminal in the arc served by brush 559, conductor 561, lower left-hand contact of sequence switch spring 323, lower right-hand contact of sequence switch spring 304, conductor 305, inner right-hand armature and back contact of relay 306, outer left-hand armature and back contact of relay 307, outer left-hand armature and back contact of relay 308, lower left-hand contact of sequence switch spring 309, armature and front contact of stepping relay 320, conductors 310 and 311, lower right-hand contact of sequence switch 312 to ground. 40 45 50 Counting relay No. 2 is energized and prepares in the well-known manner, a circuit for the No. 2' counting relay.

In position 4 of sequence switch 700, relay 702 remains energized in a locking circuit identical with the circuit above traced for brush selection, and a circuit is again completed for up-drive magnet 707 from grounded battery, winding of magnet 707, lower left-hand contact of sequence switch spring 705, left-hand armature and front contact of relay 702 to ground. The up-drive magnet is energized and causes the upward movement of the selected brush set. As soon as commutator brush 714 engages a 55 60 65 conducting portion of commutator 715, stepping relay 320 is shunted down and

allows the No. 2' counting relay to be energized. Upon the third shunting down of the stepping relay, the 0' counting relay and relay 321 in parallel are energized. Relay 321 opens the lower branch of the locking circuit of relay 702 and when, a moment later, brush 714 engages an insulating segment of commutator 715, relay 702 is de-energized, opening the circuit of up-drive magnet 707 and causing the brush set to come to rest with the selector brushes on the first terminal of the third group of trunks. Relay 702 upon deenergizing also completes a circuit from grounded battery, power magnet of sequence switch 700, lower left-hand contact of sequence switch spring 711, left-hand armature and back contact of relay 702 to ground for moving sequence switch 700 out of position 4 and into position 5.

In the sender circuit the energization of the 0' counting relay completes a circuit from grounded battery, power magnet of sequence switch 300, lower right-hand contact of sequence switch spring 331, conductor 340, left-hand armature and back contact of relay 332, conductor 334, inner right-hand armature and back contact of relay 307, armature and front contact of 0' counting relay to ground, for moving sequence switch 300 out of position 8 and into position 9. When sequence switch 300 leaves position 8 the locking circuits of the counting relays are broken and they are de-energized.

In position 5 of sequence switch 700 a circuit is completed from grounded battery, left-hand winding of relay 702, lower contacts of sequence switch spring 735, to ground. Relay 702 is energized and completes a circuit from grounded battery, power magnet of sequence switch 700, upper left-hand contact of sequence switch spring 705, left-hand armature and front contact of relay 702 to ground, for moving sequence switch 700 out of position 5 and into position 6. It is to be observed that relay 702, upon energizing, locks itself to test brush 716 by way of its right-hand armatures and the upper right-hand contact of sequence switch spring 706 as well as by way of conductor 718, and the lower right-hand contact of sequence switch spring 717.

With sequence switch 700 in position 6 and relay 702 energized, a circuit is again completed from grounded battery, winding of up-drive magnet 707, lower left-hand contact of sequence switch spring 705, left-hand armature and front contact of relay 702 to ground. The second brush is now moved upward over the terminals of the third group in search of an idle trunk. As soon as the terminals of the idle trunk are encountered, due to the absence of potential on the test terminal of such trunk, the

locking circuit of relay 702 will be broken. This relay is maintained energized an instant longer however, due to the closure of a circuit from grounded battery, left-hand 5 winding of relay 702, right-hand contacts of sequence switch spring 735, a conducting segment of commutator 719, commutator brush 733 to ground. When, an instant later, the brush 733 engages an insulating 10 segment of commutator 719, at which time the brush set will be accurately centered on the set of terminals seized, the holding circuit through the left-hand winding of relay 702 is broken and this relay deenergizes, 15 opening the circuit of up-drive magnet 707 and completing a circuit from ground, winding of the power magnet of sequence switch 700, lower left-hand contact of sequence switch spring 711, left-hand armature and 20 back contact of relay 702 to ground, for moving sequence switch 700 out of position 6 and into position 7.

In position 7 of sequence switch 700, a circuit is completed from grounded battery, 25 left-hand winding of relay 702, lower contacts of sequence switch spring 735 to ground. Relay 702 is energized and at its left-hand armature and front contact completes a circuit from grounded battery, 30 power magnet of sequence switch 700, upper left-hand contact of sequence switch spring 705, left-hand armature and front contact of relay 702 to ground for moving sequence switch 700 out of position 7 and into position 8. Relay 702 upon energization locks up through its inner right-hand armature and front contact and the lower right-hand contact of sequence switch spring 706 to the test brush of the district switch by way of 35 conductor 720 which extends directly to test terminal 193. Busy ground is also supplied from the district switch to test terminal 721 to render the trunk to the incoming switch which has been seized, unselectable by other 40 hunting office selector switches.

Referring now to the sender circuit, it will be remembered that sequence switch 300 is in position 9. Provided that the thousands and hundreds registers have been set, 50 it will be immediately moved out of position 9. If the thousands and hundreds registers have been set the side switch which controls the setting of the registers will have been advanced into position 4 or into 55 some position in advance of position 4. If the thousands and hundreds registers have not been positioned by the time sequence switch 300 reaches position 9, it will await the setting of such registers. As soon, however, as the side switch reaches position 4 60 a circuit is completed from grounded battery, power magnet of sequence switch 300, upper left-hand contact of sequence switch spring 313, conductor 350, left-hand contacts of sequence switch spring 249, con-

ductor 250, side switch brush 586 and contact No. 4 or some contact beyond No. 4, conductor 537, right-hand armature and front contact of relay 218 to ground. The closure of this circuit moves sequence switch 70 300 out of position 9 and into position 10.

As soon as sequence switch 300 reaches position 9 1/4 a circuit is completed from grounded battery, right-hand winding of relay 802, left-hand contacts of sequence switch 75 spring 803, compensating resistance 804, conductor 727, terminal 725, brush 724, lower right-hand contact of sequence switch spring 728, conductor 704, terminal 153, brush 154, lower right-hand and upper left-hand contacts of sequence switch spring 155, conductor 156, inner right-hand armature and front contact of relay 121, sender selector brush 132, and its associated contact, conductor 133, outer right-hand armature and back 80 contact of relay 239, resistance 251, upper right-hand contact of sequence switch spring 252, winding of relay 253, conductor 254, upper left-hand contact of sequence switch spring 342, outer left-hand armature and 90 back contact of relay 306, conductor 343, sender selector brush 150 and its associated contact, lower contacts of sequence switch spring 151, brush 157, terminal 158, conductor 159, lower contact of sequence switch 95 spring 729, brush 722, terminal 726, conductor 723, upper left-hand contact of sequence switch spring 805, compensating resistance 806, upper contacts of sequence switch spring 807, to ground. Relay 253 is energized in 100 this circuit. Relay 253 is marginal and will operate on 48 volts but will not operate on 24 volts. The function of relay 253 is to prevent the closure of the fundamental circuit in case an interoffice incoming selector 105 switch has been seized, until such switch has returned to its normal position and is ready for reoperation, a condition which will be hereinafter described. In the present case, however, relay 253 is energized and completes a circuit from grounded battery, winding of relay 246, armature and front contact of relay 253 to ground. Relay 246 is energized and completes a circuit from 110 grounded battery, power magnet of sequence switch 300, conductors 336 and 254, left-hand contacts of sequence switch spring 255, conductor 256, lower left-hand contact of sequence switch spring 345, outer left-hand armature and front contact of relay 246, conductors 346 and 347, upper right-hand contact of sequence switch spring 238 to ground, for moving sequence switch 300 out of position 115 120 125 130 10 and into position 12. Relay 802 was not energized upon the completion of the above traced circuit, which included relay 253, since the presence of resistance 251 prevents its operation. After the operations above described have taken place and sequence switch 300 has been advanced to posi-

- tion 12, relay 802 is energized in the fundamental circuit, which extends from grounded battery, right-hand winding of relay 802, left-hand contacts of sequence switch spring 803, resistance 804, conductor 727, terminal 725, brush 724, lower right-hand contact of sequence switch spring 728, conductor 704, terminal 153, brush 154, lower right-hand and upper left-hand contacts of sequence switch spring 155, conductor 156, inner right-hand armature and front contact of relay 121, sender selector brush 132 and its associated contact, conductor 133, outer right-hand armature and back contact of relay 239, upper right-hand contact of sequence switch spring 240, conductor 241, left-hand winding of relay 361, inner left-hand armature and back contact of relay 317, upper right-hand contact of sequence switch spring 319, winding of stepping magnet 320, armature and back contact of relay 321, inner left-hand armature and back contact of relay 306, left-hand contacts of sequence switch spring 348, conductor 343, sender selector brush 150 and its associated contact, lower contacts of sequence switch spring 151, brush 157, terminal 158, conductor 159, lower right-hand contact of sequence switch spring 729, brush 722, terminal 726, conductor 723, upper left-hand contact of sequence switch spring 805, resistance 806, upper contacts of sequence switch spring 807, to ground. Relay 802 is energized in this circuit and completes a circuit from grounded battery, power magnet of sequence switch 800, upper right-hand contact of sequence switch spring 808, left-hand armature and front contact of relay 802 to ground, for moving sequence switch 800 out of position 1 and into position 2.
- With sequence switch 800 in position 2, relay 802 completes a locking circuit for itself extending from grounded battery, right-hand winding of relay 802, right-hand armature and front contact of relay 802, conductors 809 and 810, upper left-hand contact of sequence switch brush 811, conductor 812, resistance 804 and thence over the fundamental circuit to ground as described.
- Stepping relay 320 is energized in the fundamental circuit and completes a circuit from grounded battery, winding of the No. 2 counting relay, armature and back contact of the No. 2' counting relay, thousands register brush 562, which it will be remembered is in contact with terminal No. 5, conductor 563, upper right-hand contact of sequence switch spring 351, lower right-hand contact of sequence switch spring 304, conductor 305, inner right-hand armature and back contact of relay 306, outer left-hand armature and back contact of relay 307, outer left-hand armature and back contact of relay 308, lower left-hand contact of sequence switch spring 309, armature and

front contact of relay 320, conductors 310 and 311, lower right-hand contact of sequence switch spring 312 to ground. The No. 2 counting relay is energized in this circuit and prepares, in the well-known manner, a circuit for the No. 2' counting relay. 70

The left-hand winding of overflow relay 361 is included in this circuit but the current flows in such a direction as not to allow this relay to be energized, since it is electrically polarized due to the fact that a circuit is in existence through its right-hand winding, extending from grounded battery, right-hand winding of relay 361, conductor 362, conductor 367, lower right-hand contact of sequence switch spring 341, conductors 326 and 327, to ground. In case all the trunks of a group are busy and a selector switch comes into overflow position, the flow of current through the left-hand winding of this relay will be in a direction to magnetically aid the right-hand winding in which case this relay will be energized to set up the proper circuit conditions for handling the overflow condition. A description of the operation of the system when this condition is encountered, will be given hereinafter. 80 85

With relay 802 energized in position 2 of sequence switch 800, a circuit is completed from grounded battery, winding of up-drive magnet 813, lower right-hand contact of sequence switch spring 808, left-hand armature and front contact of relay 802, to ground. In response to the upward movement of the brush shaft, the action of commutator brush 814 on commutator 815 causes the intermittent shunting down of the stepping relay in the well-known manner, and when the 0' counting relay and relay 321 are energized in parallel, at which time the third brush set of the incoming switch is in a position to be tripped, the lower branch of the fundamental circuit is opened and when, a moment later, brush 814 engages an insulating segment of commutator 815, the circuit of relay 802 is broken and this relay deenergizes, bringing the brush shaft to rest and completing a circuit from grounded battery, power magnet of sequence switch 800, lower right-hand contact of sequence switch spring 816, left-hand armature and back contact of relay 802 to ground, for moving sequence switch 800 out of position 2 and into position 3. 100 105 110 115

The energization of 0' counting relay completes a circuit from grounded battery, power magnet of sequence switch 800, lower right-hand contact of sequence switch spring 331, conductor 340, left-hand armature and back contact of relay 332, conductor 334, inner right-hand armature and back contact of relay 307, armature and front contact of the 0' counting relay to ground for mov- 120 125 130

ing this sequence switch out of position 12 and into position 13.

In position 13 of sequence switch 300, a circuit is completed from ground, upper 5 left-hand contact of sequence switch spring 312, resistance 322, inner left-hand armature and back contact of relay 306, armature and back contact of relay 321, (it being borne in mind that the counting relays were de- 10 energized when sequence switch 300 left position 12), winding of stepping relay 320, lower left-hand contact of sequence switch spring 319, to grounded battery. The purpose of this circuit is to overcome any residual magnetism of opposite polarity to the normal direction of magnetism set up in the stepping relay in its regular operation in the fundamental circuit. This opposing magnetism might be present if current over 15 the fundamental circuit had been reversed in position 12 due to the finding of an incoming selector in the overflow position.

Relay 320 is energized in the circuit just traced and completes a circuit from grounded battery, power magnet of sequence switch 25 300, lower left-hand contact of sequence switch spring 331, conductors 352 and 310, armature and front contact of relay 320, upper right-hand contact of sequence switch 30 312, to ground, for moving sequence switch 300 out of position 13 and into position 14.

With sequence switch 800 in position 3 and sequence switch 300 in position 14, the 35 fundamental circuit is again closed. This circuit is identical with that previously described for brush selection at the incoming switch and will therefore not be described in detail. Relay 802 and stepping relay 320 40 are energized in this circuit. Relay 802 completes a locking circuit for itself extending through its right-hand armature and front contact, conductors 809 and 810, the upper left-hand contact of sequence 45 switch spring 811, conductor 812, resistance 804 and thence to ground over the fundamental circuit. The energization of relay 802 also completes a circuit extending from grounded battery, winding of power magnet of sequence switch 800, upper right- 50 hand contact of sequence switch spring 808, left-hand armature and front contact of relay 802 to ground, for moving sequence switch 800 out of position 3 and into position 55 4.

In position 4 of sequence switch 800, relay 802 again completes a circuit from grounded battery, winding of up-drive magnet 813, lower right-hand contact of 60 sequence switch spring 808, left-hand armature and front contact of relay 802 to ground. Magnet 813 is energized and causes the brush shaft to be moved upwardly to accomplish group selection.

65 It is to be observed that when sequence

switch 800 reached position 3, a circuit was completed from grounded battery, winding of trip magnet 817, lower left-hand and upper right-hand contacts of sequence switch spring 807 to ground. The trip magnet was energized in this circuit to operate the trip rod so that when the brush shaft begins its upward movement, the second brush set is tripped into operative relation with the contact sets served by it.

Referring now to Fig. 8, it will be observed that as soon as the hundreds register is positioned, it being borne in mind that this register was set in position 6, a circuit is completed from grounded battery, winding of relay 564, hundreds register brush 565 and its associated No. 6 terminal to ground. Relay 564 is energized in this circuit.

The energization of stepping relay 320 above mentioned completes a circuit from grounded battery, winding of the No. 3 counting relay, armature and back contact of the No. 3' counting relay thence to the left-hand armature and front contact of relay 564 (Fig. 8), conductor 566, thousands register brush 567, which is in engagement with terminal No. 5 in its bank, conductor 568, lower right-hand contact of sequence switch spring 351, lower right-hand contact of sequence switch spring 304, conductor 305, inner right-hand armature and back contact of relay 306, outer left-hand armature and back contact of relay 307, outer left-hand armature and back contact of relay 308, upper left-hand contact of sequence switch spring 309, armature and front contact of relay 320, upper right-hand contact of sequence switch spring 312 to ground. The No. 3 counting relay is 105 energized in this circuit and prepares, in the well-known manner, a circuit for the No. 3' counting relay.

As the incoming selector switch is moved upwardly, stepping relay 320 is intermittently shunted as commutator brush 818 engages the conducting segments of commutator 819. Upon the fourth shunting down of the stepping relay, the No. 0' counting relay and relay 321 are energized 110 in parallel. Relay 321 opens the lower branch of the locking circuit of relay 802 and when, a moment later, the brush 818 engages an insulating segment of commutator 819, the locking circuit of relay 802 115 is completely broken and this relay deenergizes, opening the circuit of the up-drive magnet 813 and bringing the selected brush set to rest below the terminals of the fourth group of trunks leading to final switches. The deenergization of relay 802 also completes a circuit from grounded battery, power magnet of sequence switch 800, lower right-hand contact of sequence switch 120 spring 816, left-hand armature and back 125 spring 817 to ground.

contact of relay 802 to ground for moving sequence switch 800 out of position 4 and into position 5.

The energization of the No. 0' counting relay completes a circuit from grounded battery, power magnet of sequence switch 300, lower right-hand contact of sequence switch spring 331, conductor 340, left-hand armature and back contact of relay 332, conductor 334, inner right-hand armature and back contact of relay 307, to ground at the armature and front contact of the No. 0' counting relay, for moving sequence switch 300 out of position 14 and into position 16.

With sequence switch 800 in position 5, a circuit is completed from grounded battery, left-hand winding of relay 802, upper left-hand and lower right-hand contacts of sequence switch spring 820 to ground. Relay 802 is energized in this circuit and locks up through its right-hand winding and right-hand armature and front contact to test brush 821 by way of the upper contacts of sequence switch spring 822. The energization of relay 802 completes a circuit from grounded battery, power magnet of sequence switch 800, upper right-hand contact of sequence switch spring 808, left-hand armature and front contact of relay 802 to ground for moving sequence switch 800 out of position 5 and into position 6.

In position 6 of sequence switch 800, trunk hunting takes place, the up-drive magnet being energized over a circuit extending from grounded battery, winding of up-drive magnet 813, lower contact of sequence switch spring 808, left-hand armature and front contact of relay 802 to ground. The test terminals of busy trunks will be characterized by the presence of ground potential thereon and as soon as an idle trunk is reached, the absence of ground on the test terminal associated with test brush 821 will open the circuit through the right-hand winding of relay 802. Relay 802 is held energized a moment longer, however, due to the closure of a circuit from grounded battery, left-hand winding of relay 802, upper contacts of sequence switch spring 820, a conducting portion of commutator 824, commutator brush 823, to ground. As soon as brush 823 engages an insulating portion of commutator 824, at which time the brush set will be accurately centered on the terminals of the selected trunk, relay 802 is deenergized and opens at its left-hand armature the circuit of up-drive magnet 813, thus causing the brush shaft to come to rest. The deenergization of relay 802 also completes a circuit from grounded battery, power magnet of sequence switch 800, lower right-hand contact of sequence switch spring 816, left-hand armature and back contact of relay 802 to ground for moving this sequence

switch out of position 6 and into position 7.

In position 7 of sequence switch 800, a circuit is completed from grounded battery, right-hand winding of relay 802, upper right-hand contact of sequence switch spring 823, brush 827, terminal 828, conductors 829 and 902, upper left-hand and lower right-hand contacts of sequence switch spring 903, conductor 904, thence by way of a divided circuit to conductor 905, one branch of this parallel circuit extending through the left-hand winding of relay 906, and the other branch extending by way of the upper right-hand and lower left-hand contacts of sequence switch spring 907, resistance 908 and the lower right-hand contact of sequence switch spring 909, conductor 905, thence by way of the upper left-hand contact of sequence switch spring 910 and conductor 911 to ground. Relay 802 is energized in this circuit and locks up through its right-hand armature and front contact to ground by way of the left-hand contacts of sequence switch spring 822. The energization of relay 802 completes a circuit from grounded battery, power magnet of sequence switch 800, upper right-hand contact of sequence switch spring 808, left-hand armature and front contact of relay 802 to ground, for moving sequence switch 800 out of position 7 and into position 8. In position 8, the locking circuit of relay 802 is extended to brush 827 and thence to ground as described, by way of conductor 834 and the lower left-hand contact of sequence switch spring 833.

With sequence switch 800 in position 8, a circuit is completed from grounded battery, right-hand winding of relay 912 (Fig. 13) lower left-hand contact of sequence switch spring 913, upper left-hand contact of sequence switch spring 914, conductor 832, terminal 831, brush 830, lower right-hand and upper left-hand contacts of sequence switch spring 803, resistance 804 and thence over the fundamental circuit previously described, returning by way of conductor 723, upper left-hand contact of sequence switch spring 805, resistance 806 and the upper contacts of sequence switch spring 807 to ground. Relay 912 and stepping relay 320 are energized in this circuit. Relay 912, upon energization, completes a circuit from grounded battery, winding of relay 915, lower right-hand contact of sequence switch spring 916, left-hand armature and front contact of relay 912 to ground. Relay 915 is energized and locks itself to the test conductor 826 to which ground is supplied, as previously described, from the district switch.

Relay 915, upon energization, completes a circuit from grounded battery, power magnet of sequence switch 900, upper left-hand contact of sequence switch spring 917,

- right-hand armature and front contact of relay 915 to ground, for moving sequence switch 900 out of position 1 and into position 2. It is to be observed that relay 912, 5 upon energization, locked itself to the fundamental circuit by way of its right-hand armature and front contact and the lower right-hand contact of sequence switch spring 913.
- 10 Referring now to the sender circuit (Fig. 6), the energization of stepping relay 320 completes a circuit from grounded battery, winding of the No. 1 counting relay, armature and back contact of the No. 1' counting 15 relay, thence to the No. 6 terminal in the arc served by hundreds register brush 569, it being remembered that this register has its brushes in contact with their respective No. 6 terminals, conductor 570, lower left-hand 20 contact of sequence switch spring 351, lower right-hand contact of sequence switch spring 304, conductor 305, inner right-hand armature and back contact of relay 306, outer left-hand armature and back 25 contact of relay 307, outer left-hand armature and back contact of relay 308, lower left-hand contact of sequence switch spring 309, armature and front contact of stepping relay 320, conductors 310 30 and 311, lower right-hand contact of sequence switch spring 312 to ground. The No. 1 counting relay is energized in this circuit and prepares, in the well-known manner, the circuit of the No. 1' counting relay.
- 35 With sequence switch 900 in position 2 and relay 912 energized, a circuit is completed from grounded battery, winding of high speed up-drive magnet 918, upper left-hand contact of sequence switch spring 919, left-hand armature and front contact of relay 912 to ground. The brush shaft is now moved upward in a brush selecting movement. As the brush shaft is moved upward, the locking circuit to relay 912 is extended 40 to ground by way of commutator brush 920 and commutator 921 as soon as the commutator brush engages the first conducting segment of commutator 921. Stepping relay 320 is shunted down due to the closure of 45 this circuit and allows the No. 1' counting relay to operate. Upon the second shunting down of the stepping relay, the No. 0' counting relay and relay 321 are energized, relay 321 opening the lower branch of locking 50 circuit of relay 912. When, a moment later, commutator brush 920 engages an insulating portion of commutator 921, at which time the brushes will be accurately positioned for tripping, the holding circuit of relay 912 is 55 broken and this relay deenergizes, opening the circuit of up-drive magnet 918 to bring the brush shaft to rest, and at the same time completing a circuit from grounded battery, power magnet of sequence switch 900, upper 60 right-hand contact of sequence switch spring 922, left-hand armature and back contact of relay 912 to ground, for moving sequence switch 900 out of position 2 and into position 3.
- The energization of the No. 0' counting relay completes a circuit from grounded battery, winding of the power magnet of sequence switch 300, lower right-hand contact of sequence switch spring 331, conductor 340, left-hand armature and back contact of relay 332, conductor 334, inner right-hand armature and back contact of relay 307, front contact and armature of the No. 0' counting relay to ground, for moving sequence switch 300 out of position 16 and 70 into position 17. As soon as switch 300 leaves position 16, the circuits of the counting relays are broken and these relays are deenergized.
- 75 Providing now that the tens and units registers have been set, and that the register controlling side switch has advanced to position 9, a circuit is completed from grounded battery, power magnet of sequence switch 300, lower left-hand contact of sequence switch spring 313, conductors 353 and 354, upper left-hand contact of sequence switch spring 257, conductor 258, side switch brush 586 and its associated contact, conductor 537, right-hand armature and front contact 80 of relay 218 to ground, for moving sequence switch 300 out of position 17 and into position 18.
- 85 The manner in which the register controlling side switch is advanced into position 9 will now be described. It is obvious that after the units register is set, the side switch will be advanced out of position 5 and into position 6 in the manner previously described. With the class sequence switch 90 300 in position 7, which is the position in which a full mechanical selection is to be made and no stations impulses are to be sent, circuits will be completed for moving the side switch out of position 6 and into position 9, as soon as the sender sequence switch reaches position 2. At this time a circuit is completed from grounded battery, winding of side-switch stepping magnet 520, armature and back contact of magnet 520, conductor 521, left-hand armature and back contact of relay 503, side-switch brush 522 and its sixth contact, conductors 575 and 576, right-hand contacts of sequence switch 95 261, conductor 262, lower right-hand contact of sequence switch spring 364, conductor 315, left-hand armature and front contact of relay 223, conductor 227, outer left-hand armature and front contact of 100 relay 543, to ground. Stepping magnet 520 is energized and advances the side switch 105 into position 7.
- 110 In position 7 a circuit is completed from grounded battery, winding of side switch stepping magnet 520, armature and back 115 contact of relay 543, to ground. Stepping magnet 520 is energized and advances the side switch 120 into position 8.
- 120 In position 8 a circuit is completed from grounded battery, winding of side switch stepping magnet 520, armature and back 125 contact of relay 543, to ground. Stepping magnet 520 is energized and advances the side switch 130 into position 9.

- contact of magnet 520, conductor 521, left-hand armature and back contact of relay 503, side-switch brush 522 and its seventh contact, conductors 577 and 578, lower left-hand and upper right-hand contacts of sequence switch spring 261, to ground over the path described. Stepping magnet 520 is energized and advances the side switch into position 8.
- 10 In position 8, a circuit is completed from grounded battery, winding of magnet 520, armature and back contact of magnet 520, conductor 521, left-hand armature and back contact of relay 503, side-switch brush 522 and its eighth contact, conductors 579 and 580, upper contacts of sequence switch spring 261, to ground over the path described. Stepping magnet 520 is energized and advances the side switch into position 9.
- 15 Referring now to the final switch, in position 3 of sequence switch 900, a circuit is completed from grounded battery, winding of trip magnet 923, upper right-hand contact of sequence switch spring 924, to ground. The trip magnet is operated in this circuit so that upon subsequent upward movement of the brush shaft, the second set of brushes will be tripped into operative 20 relation with the terminals served by them.
- 25 As soon as sequence switch 300 reaches position 18, the fundamental circuit is again completed over a path identical with the one just traced in connection with brush selection and line relay 912 and stepping relay 320 are energized. Relay 912 locks up through its right-hand armature and front contact, as before and at the same time completes a circuit from grounded battery, 30 power magnet of sequence switch 900, upper left-hand contact of sequence switch 922, left-hand armature and front contact of relay 912 to ground, for moving sequence switch 900 out of position 3 and into position 4.
- 35 In position 4, the circuit of high speed up-drive magnet 918 is again completed and the brush shaft is started upward.
- 40 The energization of stepping relay 320 completes a circuit from grounded battery, winding of the No. 7 counting relay, armature and back contact of the No. 7' counting relay, tens register brush 571, which is in engagement with contact No. 7 in the 45 arc served by it, conductor 572, upper left-hand and lower right-hand contacts of sequence switch spring 304, conductor 305, inner right-hand armature and back contact of relay 306, outer left-hand armature and back contact of relay 307, outer left-hand armature and back contact of relay 308, upper left-hand contact of sequence switch spring 309, armature and front contact of relay 320, upper right-hand contact 50 of sequence switch spring 312 to ground.

The No. 7 counting relay is energized in this circuit and prepares a circuit for the No. 7' counting relay.

As the brush shaft is moved upward, the stepping relay is intermittently shunted down as commutator brush 925 engages conducting segments of commutator 926. The eighth shunting of the stepping relay allows the No. 0' counting relay and relay 321 to become energized. Relay 321, upon energization, opens the lower branch of the locking circuit of relay 912 and when, a moment later, brush 925 engages an insulating segment of commutator 926, the holding circuit of relay 912 is broken and this relay deenergizes, bringing the brush shaft to rest with the second brush set in operative relation to the eighth group of terminals served by it. The deenergization of relay 912 also completes a circuit from grounded battery, 55 power magnet of sequence switch 900, upper right-hand contact of sequence switch spring 922, left-hand armature and back contact of relay 912 to ground, for moving sequence switch 900 out of position 4 and 60 into position 5.

The energization of the No. 0' counting relay completes a circuit from grounded battery, winding of relays 306 and 332 in series, right-hand contacts of sequence switch 65 spring 355, conductors 356 and 334, inner right-hand armature and back contact of relay 307 to ground at the armature and front contact of the No. 0' counting relay. Relays 306 and 332 are energized in this circuit and lock up by way of the inner right-hand armature and front contact of relay 332 to conductor 347 and thence by way of the upper right-hand contact of sequence switch spring 238 to ground. The energization of relay 306 also completes a circuit from ground, outer right-hand armature and front contact of relay 306, winding of relay 357, winding of relay 317 to grounded battery. Relays 357 and 317 are energized 100 in this circuit. The energization of relay 357 completes a circuit from grounded battery, power magnet of sequence switch 300, upper left-hand contact of sequence switch 105 spring 331, conductor 358, outer left-hand armature and front contact of relay 357, conductors 359 and 360, lower left-hand contact of sequence switch spring 341, conductors 326 and 327 to ground, for moving sequence switch 300 out of position 18, 110 through position 1, and into position 2 of its second revolution.

With sequence switch 900 in position 5 and with sequence switch 300 in position 2 of its second revolution, and with relays 115 306, 332, 317 and 357 energized, the fundamental circuit is again completed to control the selection of the wanted line at the final switch. The fundamental circuit extends from grounded battery, right-hand winding 120 130

- of relay 912, lower left-hand contact of sequence switch spring 913, upper left-hand contact of sequence switch spring 914, conductor 832, terminal 831, brush 830, lower 5 left-hand and upper right-hand contacts of sequence switch spring 803, resistance 804, conductor 727, terminal 725, brush 724, lower right-hand contact of sequence switch spring 728, conductor 704, terminal 153, 10 brush 154, lower right-hand and upper left-hand contacts of sequence switch spring 155, conductor 156, inner right-hand armature and front contact of relay 121, sender selector brush 132 and its associated contact, conductor 133, outer right-hand armature and back contact of relay 239, upper right-hand contact of sequence switch spring 240, conductor 241, left-hand winding of relay 361, inner left-hand armature and front contact 15 of relay 317, lower right-hand contact of sequence switch spring 319, winding of stepping relay 320, armature and back contact of relay 321, inner left-hand armature and front contact of relay 306, upper right-hand 20 and lower left-hand contacts of sequence switch spring 348, conductor 343, and thence to ground over the path previously described. Relay 912 is energized in this circuit and locks up through its right-hand 25 armature and front contact and the lower right-hand contact of sequence switch spring 913, to ground over the fundamental circuit. Relay 912 upon energizing also completes a circuit from grounded battery, power magnet of sequence switch 900, upper left-hand contact of sequence switch spring 922, left-hand armature and front contact of relay 912, to ground for moving sequence switch 900 out of position 5 and into position 6. 30 In position 6 of sequence switch 900, the circuit of low speed up-drive magnet 927 is completed, extending from grounded battery, winding of magnet 927, upper left-hand contact of sequence switch spring 916, 35 left-hand armature and front contact of relay 912 to ground. Under the control of magnet 927 the brush set is again moved upward. Referring now to the sender circuit, Fig. 40 6, the energization of stepping relay 320 completes a circuit from grounded battery, winding of the No. 8 counting relay, armature and back contact of the No. 8' counting relay, thence to terminal No. 8 in the arc 45 served by units register brush 573, which, it will be remembered, has been set so that its brushes engage the No. 8 terminals in the respective arcs served by them, conductor 574, outer right-hand armature and back 50 contact of relay 259, (Fig. 3), conductor 260, upper left-hand and lower right-hand contacts of sequence switch spring 363 (Fig. 6), conductor 394, inner right-hand armature and front contact of relay 306, outer 55 left-hand armature and back contact of re- lay 307, outer left-hand armature and back contact of relay 308, upper left-hand contact of sequence switch spring 309, armature and front contact of stepping relay 320, upper right-hand contact of sequence switch spring 312, to ground. Counting relay No. 8 is energized in this circuit and prepares, in the well-known manner, a circuit for the No. 8' counting relay. 60 As commutator brush 920 engages conducting segments of commutator 921, the locking circuit of relay 912 is intermittently extended to ground by way of the commutator with the result that stepping relay 320 is intermittently shunted down to allow the successive actuation of the counting relays. Upon the ninth shunting down of the stepping relay 320, at which time the brushes will be in engagement with the ninth line in the selected group, the 0' counting relay 65 and relay 321 are energized. The energization of relay 321 opens the lower branch of the locking circuit of relay 912 and when, a moment later, commutator brush 920 engages an insulating segment of commutator 921, at which time the brush set will be accurately centered on the terminals of the desired line, the locking circuit of relay 912 is broken and this relay deenergizes, opening 70 at its left-hand armature the circuit of up-drive magnet 927 and at the same time completing a circuit from grounded battery, power magnet of sequence switch 900, upper right-hand contact of sequence switch spring 922, left-hand armature and back contact of relay 912 to ground, for moving sequence switch 900 out of position 6 and into position 7. The energization of the 0' counting relay 75 completes a circuit from grounded battery, power magnet of sequence switch 300, upper right-hand contact of sequence switch spring 331, left-hand armature and front contact of relay 332, conductor 334, inner right-hand armature and back contact of relay 307, armature and front contact of the 0' counting relay to ground, for moving sequence switch 300 out of position 2 and into position 4. As soon as sequence switch 80 leaves position 2 the circuits of the counting relays are opened and these relays deenergize. 85 As soon as sequence switch 900 reaches position 7, a circuit is completed from grounded battery, right-hand winding of relay 912, lower left-hand contact of sequence switch spring 913, upper left-hand contact of sequence switch spring 914, conductor 832, terminal 831, brush 830, lower right-hand and upper left-hand contacts of sequence switch spring 803, resistance 804, conductor 727, terminal 725, brush 724, lower right-hand contact of sequence switch spring 728, conductor 704, terminal 153, brush 154, lower 90 right-hand and upper left-hand contacts of 95 relay 307, outer left-hand armature and back contact of relay 308, upper left-hand contact of sequence switch spring 309, armature and front contact of stepping relay 320, upper right-hand contact of sequence switch spring 312, to ground. Counting relay No. 8 is energized in this circuit and prepares, in the well-known manner, a circuit for the No. 8' counting relay. 100

- sequence switch spring 155, conductor 156, inner right-hand armature and front contact of relay 121, sender selector brush 132 and its associated contact, conductor 133, outer 5 right-hand armature and back contact of relay 239, upper right-hand contact of sequence switch spring 240, conductor 241, inner right-hand armature and front contact of relay 317, upper right-hand contact 10 of sequence switch spring 318, winding of stepping relay 320, armature and back contact of relay 321, inner left-hand armature and front contact of relay 306, upper right-hand and lower left-hand contacts of sequence switch spring 348, conductor 343, sender selector brush 150 and its associated contact, lower contacts of sequence switch spring 351, brush 157, terminal 158, conductor 159, lower right-hand contact of sequence switch spring 729, brush 722, terminal 726, conductor 723, upper right-hand contact of sequence switch spring 805, resistance 806, upper contacts of sequence switch spring 807, to ground. Line relay 25 912 and stepping relay 320 are energized in this circuit. Relay 912 upon energization locks itself to the fundamental circuit by way of its right-hand armature and front contact and the lower right-hand contact of sequence switch spring 913 and at its left-hand armature completes a circuit from grounded battery, power magnet of sequence switch 900, upper left-hand contact of sequence switch spring 922, left-hand armature and front contact of relay 912, to ground. The completion of this latter circuit causes sequence switch 900 to move out of position 7 and into position 9.
- The energization of the stepping relay 40 320 at this time completes a circuit from grounded battery, winding of the zero counting relay, right-hand contacts of sequence switch spring 363, conductor 394, inner right-hand armature and front contact of relay 306, outer left-hand armature and back contact of relay 307, outer left-hand armature and back contact of relay 308, lower left-hand contact of sequence switch spring 309, armature and front contact of stepping relay 320, conductors 310 and 311, lower right-hand contact of sequence switch spring 312, to ground. The zero counting relay is energized in this circuit and prepares a circuit for the zero 45 prime counting relay. As soon as sequence switch 900 leaves position $7\frac{1}{2}$, the fundamental circuit is broken and relay 320 de-energizes and allows the zero prime counting relay to be energized. A circuit is then completed from grounded battery, power magnet of sequence switch 300, upper right-hand contact of sequence switch spring 331, left-hand armature and front contact of relay 332, conductor 334, inner right-hand armature and back contact of relay 307, to

ground, at the armature and front contact of the zero prime counting relay, for moving sequence switch 300 out of position 4 and into position 6 of its second revolution. Since no station impulses are to be sent, sequence switch 300 is then moved through positions 6, 8 and 10 and into position 12, by means of circuits which will be hereinafter described. 70

Since the connector switch shown in Fig. 75 13 is not arranged for through dialing to a private branch exchange, the locking circuit of relay 802 (Fig. 12) is maintained by way of conductors 829 and 928 and the upper right-hand contact of sequence switch spring 80 910, to ground, after sequence switch 900 leaves position 8, since the original locking circuit by way of the contacts of sequence switch spring 903 is opened at this time. In case the final connector were to be used in 85 connection with an arrangement whereby impulses are sent to a recording apparatus at a P. B. X., conductor 928 would be omitted and the ground for holding relay 802 energized would be supplied to conductor 829 90 by means of the recording apparatus or switching devices at the P. B. X.

When sequence switch 900 reaches position $7\frac{1}{2}$, the locking circuit of relay 912 is maintained by way of conductor 929 and 95 the lower right-hand contact of sequence switch spring 924, to ground, so that this relay remains energized after its original locking circuit is broken at the lower right-hand contact of sequence switch 913. 100

When sequence switch 900 reaches position 9, a circuit is completed from grounded battery, right-hand contacts of sequence switch spring 907, left-hand winding of relay 906, lower right-hand contact of sequence switch spring 919, left-hand armature and front contact of relay 912, to ground. Relay 906 is energized in this circuit and completes a circuit from grounded battery, power magnet of sequence switch 105 900, lower right-hand contact of sequence switch spring 922, conductor 930, left-hand armature and front contact of relay 906, lower left-hand contact of sequence switch spring 910, to ground, for moving sequence 110 switch 900 out of position 9 and into position 11. 115

It is to be observed that as soon as test relay 906 was energized it completed a locking circuit for itself from ground, lower 120 left-hand contact of sequence switch spring 931, conductor 932, winding of private branch exchange test relay 933, right-hand winding of relay 906, right-hand armature and front contact of relay 906, upper right-hand contact of sequence switch spring 934, test brush 935, test terminal 936, conductor 937, to grounded battery, provided that the called line is busy. 125

Assuming now that the line called is a 130

- direct line and that it is idle, no potential is supplied to test terminal 936 and therefore relay 906 is not maintained energized, nor is relay 933 caused to energize. Relay 5 906 thereupon deenergizes and completes a circuit from grounded battery, power magnet of sequence switch 900, lower left-hand contact of sequence switch spring 922, left-hand armature and back contact of relay 10 906, lower left-hand contact of sequence switch spring 910, to ground, for moving sequence switch 900 out of position 11, through position 12, and into position 14. It is to be noted that as soon as sequence 15 switch 900 left position 9, upon the energization of relay 906, the locking circuit of relay 912 was broken and this relay was deenergized. Therefore, as soon as sequence switch 900 reaches position 14 it will be immediately moved out of position 14, due to the completion of a circuit from grounded battery, power magnet of sequence switch 900, upper right-hand contact of sequence switch spring 922, left-hand armature and 20 back contact of relay 912, to ground. The completion of this circuit drives sequence switch 900 out of position 14 and into position 15, which is the talking position.
- It will now be assumed that the line called 30 is a direct line, but that it is busy. In this case sufficient potential will be found on test terminal 936 to cause relay 906 to remain energized after the sequence switch leaves position 10 and to cause the energization of relay 933. Due to the energized condition 35 of relay 906, the sequence switch 900 is allowed to come to rest in position 11. Relay 912 was deenergized as before when the sequence switch left position 9. A circuit is 40 therefore completed from grounded battery, winding of sequence switch magnet 900, upper right-hand contact of sequence switch spring 922, left-hand armature and back contact of relay 912, to ground, for moving sequence switch 900 out of position 11 and into position 12.
- In position 12 of the sequence switch, a circuit is completed from grounded battery, right-hand winding of relay 912, lower left-hand contact of sequence switch spring 913, lower left-hand contact of sequence switch spring 914, conductor 930, left-hand armature and front contact of relay 906, lower left-hand contact of sequence switch spring 55 910, conductor 911, to ground. Relay 912 is energized and locks up through its right-hand armature and front contact to ground by way of conductor 929. The energization of relay 912 completes a circuit from 60 grounded battery, power magnet of sequence switch 900, upper left-hand contact of sequence switch spring 922, left-hand armature and front contact of relay 912, to ground, for moving sequence switch 900 out of position 12 and into position 14.

A circuit is now completed from grounded battery, down-drive magnet 938, upper right-hand contact of sequence switch spring 919, left-hand armature and front contact of relay 912, to ground. Under the 70 control of magnet 938, the brush shaft is restored to its normal position. As soon as the switch reaches its normal position, the engagement of commutator brush 939 with commutator segment 940 completes a circuit 75 from grounded battery, power magnet of sequence switch 900, upper right-hand contact of sequence switch spring 917, conducting segment 940, brush 939, to ground, for moving the sequence switch out of position 14 and into position 17. As soon as the sequence switch leaves position 14, the circuit of the down-drive magnet 938 is opened and this magnet deenergizes. 80

It is to be observed that in position 14 of the sequence switch, relay 906 is maintained energized by a circuit extending from grounded battery, right-hand contacts of sequence switch spring 907, left-hand winding of relay 906, conductor 905, lower right-hand contact of sequence switch spring 919, left-hand armature and front contact of relay 912 to ground. As soon as the sequence switch leaves position 14 the locking circuit 85 of relay 912 is broken and this relay deenergizes.

In position 17 of sequence switch 900, relay 906 is intermittently energized in a circuit extending from grounded battery, right-hand contacts of sequence switch spring 907, left-hand winding of relay 906, lower left-hand contact of sequence switch spring 909, interrupter 941, to ground. Upon each energization of relay 906, busy tone will be supplied to the calling subscriber from a source 100 of busy tone 942, lower right-hand contact of sequence switch spring 934, right-hand armature and front contact of relay 906, the upper left-hand contact of sequence switch spring 943, thence over the ring side of the line, through the various switches, which will have been advanced to talking positions, as will be later described, through the substation set of the calling subscriber, returning by way of the tip conductor, thence 105 by way of the left-hand contacts of sequence switch spring 914, conductor 930, left-hand armature and front contact of relay 906, resistance 944, upper left-hand and lower right-hand contacts of sequence switch 110 spring 907, to grounded battery. This will inform the calling subscriber that the wanted line is busy and he will replace his receiver, causing disconnection in a manner 115 to be hereinafter described.

In case the call had been extended to the final connector switch from an operator's district selector, the intermittent operation of relay 906 in position 17 of sequence switch 900 completes a circuit from grounded bat- 120 125 130

tery, lower right-hand and upper left-hand contacts of sequence switch spring 907, resistance 944, left-hand armature and front contact of relay 906, conductor 930, left-hand contacts of sequence switch spring 914, and thence over the tip conductor to operate a supervisory relay in the tip side of the operator's repeating coil, to inform such operator that the line wanted is busy. In 10 this case, the connection would then be restored under the control of the operator.

It will now be assumed that the number wanted is that of a private branch exchange, to which a number of trunks extend from 15 the final connector contact bank.

Upon the completion of units selection, the brush set of the final switch will be resting on the terminals of the first trunk of the group of trunks leading to the wanted 20 P. B. X. It will be assumed that this trunk is idle. Relay 906 will be energized in position 9 of the sequence switch as previously described and cause the sequence switch to move out of position 9, through position 10 25 and into position 11. The potential found on test terminal 936 is not high enough to allow sufficient current to flow through the locking circuit of relay 906 to allow this relay to remain energized or to allow relay 30 933 to become energized. Therefore, in position 11 of sequence switch 900, with relays 933 and 906 deenergized the sequence of operations will be the same as in the case of an idle direct line and sequence switch 900 35 will advance into position 15 in the manner previously described.

It will now be assumed that the line wanted is a P. B. X. line and that the first 40 P. B. X. line in the group is busy. In this case the sequence switch is moved out of position 9 upon the energization of relay 906 in a manner identical with that previously described. Such potential is now found on test terminal 936, however, that 45 when sequence switch 900 leaves position 9, relay 906 remains locked up through the circuit previously described. There is not sufficient current flow, however, to allow relay 933, which is marginal, to be energized. 50 As soon as sequence switch 900 leaves position 9, the locking circuit of relay 912 is broken and this relay deenergizes, but as soon as sequence switch 900 reaches position 10, relay 912 is again energized by a circuit 55 extending from grounded battery, right-hand winding of relay 912, left-hand contacts of sequence switch spring 913, armature and back contact of relay 933, conductor 930, left-hand armature and front contact of relay 906, lower left-hand contact of sequence switch spring 910, conductor 911 to ground. In this case when sequence switch 900 reaches position 11, it remains in this position since relays 912 and 60 65 906 are both energized at this time.

In position 11 of sequence switch 900, a circuit is completed from grounded battery, winding of slow-speed up-drive magnet 927, upper left-hand contact of sequence switch spring 916, left-hand armature and front contact of relay 912, to ground. The brush shaft is now moved upward in a hunting movement to select an idle trunk. If no idle trunk is encountered progress will continue until the last line of the group is 70 reached at which time the same potential will be found on test terminal 936 as in the case of a busy direct line. In this case P. B. X. relay 933 will energize and open the holding circuit of relay 912 which will 75 deenergize and move the sequence switch out of position 11. The restoration of this switch and the giving out of the busy condition will then take place in the same manner as above described in the case of the 80 testing operation in connection with busy direct lines.

If the last line of the group is idle, relays 933 and 906 will both deenergize when the brush set reaches such line and the sequence 85 switch will advance into position 15 in the manner above described in connection with the testing operations of idle direct lines.

If an idle P. B. X. line other than the last line of the group is encountered during 90 the hunting operation, no potential will be found on the test terminal, as soon as test brush 935 engages terminal 936 of such line, and therefore relay 933 is deenergized. Relay 933 opens the circuit through the 95 right-hand winding of relay 912. Relays 912 and 906 are, however, maintained energized a moment longer due to the closure of a circuit from grounded battery, left-hand winding of relay 912, right-hand contacts of sequence switch spring 903, left-hand winding of relay 906, upper left-hand contact of sequence switch spring 909, a conducting segment of commutator 945, commutator brush 939, to ground. As soon 100 as brush 939 engages an insulating segment of commutator 945, at which time the selected brush set will be accurately centered on the terminals which it has seized, the above traced circuit will be opened and 105 relays 912 and 906 deenergized and cause the advance of sequence switch 900 into position 15 in the manner described in connection with the testing of an idle direct 110 line.

Referring now to Fig. 6, it will be remembered that sequence switch 300 was moved out of position 4 and into position 6 at the time that sequence switch 900 left position $7\frac{1}{2}$. As soon as sequence switch 300 leaves position 4 the locking circuit of the zero and the zero prime counting relays is opened and these relays deenergize. However, as soon as sequence switch 300 reaches position 5 a circuit is completed from 115 120 125 130

- grounded battery, winding of the zero counting relay, winding of the zero prime counting relay and relay 321 in parallel, upper right hand contact of sequence switch 5 spring 329, conductor 358, outer left-hand armature and front contact of relay 357, conductor 359, conductor 365, left-hand contacts of sequence switch spring 355, conductors 366 and 576, right-hand contacts 10 of sequence switch spring 261, conductor 262, lower right-hand contact of sequence switch spring 364, conductor 315, left-hand armature and front contact of relay 223, conductor 227, outer left-hand armature and 15 front contact of relay 543, to ground. The zero and zero prime counting relays and relay 321 are energized in this circuit and remain energized until sequence switch 300 leaves position 10.
- 20 As soon as the zero prime counting relay is energized, a circuit is completed from grounded battery, power magnet of sequence switch 300, upper right-hand contact of sequence switch spring 331, left-hand 25 armature and front contact of relay 332, conductor 334, inner right-hand armature and back contact of relay 307, armature and front contact of the zero prime counting relay, to ground. The completion of this 30 circuit moves sequence switch 300 out of position 6 and through positions 8, 9, and 10, and into position 12.
- Referring now to Fig. 12, it will be seen 35 that when the final sequence switch 900 goes into talking position, which is position 15, the locking circuit of relay 802 is broken at the upper right-hand contact of sequence switch spring 910. Relay 802 thereupon deenergizes and completes a circuit from 40 grounded battery, power magnet of sequence switch 800, lower right-hand contact of sequence switch spring 816, left-hand armature and back contact of relay 802, to ground, for moving sequence switch 800 out 45 of position 8 and into position 9.
- With sequence switch 800 in position 9 and with sequence switch 300 in position 12 of its second revolution, a circuit is completed from grounded battery, right-hand winding 50 of relay 802, conductor 835, lower right-hand and upper left-hand contacts of sequence switch spring 807, resistance 806, upper left-hand contact of sequence switch spring 805, conductor 723, terminal 726, 55 brush 722, lower right-hand contact of sequence switch spring 729, conductor 159, terminal 158, brush 157, lower contacts of sequence switch spring 151, sender selector brush 150 and its associated contact, conductor 343, lower left-hand and upper right-hand contacts of sequence switch spring 348, inner left-hand armature and front contact 60 of relay 306, armature and back contact of relay 321, winding of stepping relay 320, 65 lower right-hand contact of sequence switch
- spring 319, inner left-hand armature and front contact of relay 317, left-hand winding of relay 361, conductor 241, upper right-hand contact of sequence switch spring 240, outer right-hand armature and back contact 70 of relay 239, conductor 133, sender selector brush 132 and its associated contact, inner right-hand armature and front contact of relay 121, conductor 156, upper left-hand and lower right-hand contacts of sequence switch 75 spring 155, brush 154, terminal 153, conductor 704, lower right-hand contact of sequence switch spring 728, brush 724, terminal 725, conductor 727, resistance 804, conductor 812, lower contacts of sequence switch spring 820, to ground. Relay 802, stepping relay 320 and polarized overflow relay 361 are energized in this circuit.
- It will be observed that the direction of current flow in the fundamental circuit just traced, is in the opposite direction to that in which it normally flows in case of selections. For this reason the left-hand winding of relay 361 now magnetically aids the right-hand winding, and this relay is therefore energized. The energization of relay 361 completes a circuit from grounded battery, winding of relay 307, inner left-hand armature and front contact of relay 357, armature and front contact of relay 361, to 95 ground. Relay 307 is energized in this circuit and locks up through its inner left-hand armature and front contact to conductor 367 until sequence switch 300 leaves position 12.
- With stepping relay 320 energized and with relay 307 energized, a circuit is completed from grounded battery, winding of the zero counting relay, outer left-hand armature and front contact of relay 307, outer 100 left-hand armature and back contact of relay 308, lower left-hand contact of sequence switch spring 309, armature and front contact of stepping relay 320, conductors 310 and 311, and lower right-hand contact of sequence switch spring 312, to ground. The zero counting relay is energized in this circuit and prepares circuits for the zero prime counting relay and relay 321.
- Relay 802 upon energization completes a 105 circuit from grounded battery, winding of power magnet of sequence switch 800, upper left-hand contact of sequence switch spring 808, left-hand armature and front contact of relay 802, to ground, for moving sequence switch 800 out of position 9 and into position 110 110.
- As soon as sequence switch 800 leaves position 9, the energizing circuit for relays 802, 320 and 361 is opened and these 115 relays deenergize. The deenergization of stepping relay 320 allows the zero prime counting relay to operate in the well known manner. The energization of the zero prime counting relay at this time com-

plete circuits for relays 239 and 263 (Fig. 3), extending from grounded battery, the windings of these relays, respectively, thence in parallel to conductor 264, right-hand armature and back contact of relay 333, inner right-hand armature and front contact of relay 307, armature and front contact of the zero prime counting relay, to ground. Relays 239 and 263 are energized in this circuit and lock up through the inner right-hand armature and front contact of relay 239, to ground, by way of the upper right-hand contact of sequence switch spring 238. The energization of relay 239 opens at its outer left-hand armature the holding circuit of relay 152 (Fig. 2) and relay 152 deenergizes, opening the circuit through the right-hand winding of relay 107 and allowing this relay to deenergize. Relay 107 upon deenergization completes a circuit from grounded battery, power magnet of sequence switch 100, upper right-hand contact of sequence switch spring 116, inner right-hand armature and back contact of relay 107, lower contact of sequence switch spring 117, to ground, for moving sequence switch 100 out of position 10 and into position 11.

As soon as sequence switch 100 leaves position 10½, the impulse circuit into the sender by way of leads 129 and 124, is opened at the upper left-hand contacts of sequence switch springs 128 and 125, respectively. As a result of the opening of the impulse circuit, relay 215 is deenergized, causing in turn the deenergization of relays 217 and 218. With relays 215 and 218 deenergized, a circuit is completed from grounded battery, winding of wipe-out relay 259, conductor 265, right-hand contacts of sequence switch spring 266, inner left-hand armature and back contact of relay 218, armature and back contact of relay 215, to ground. Relay 259 is energized in this circuit and locks up to ground through its inner left-hand armature and front contact by way of the upper right-hand contact of sequence switch spring 238.

The energization of relay 259 completes a circuit from grounded battery, power magnet of sequence switch 300, upper right-hand contact of sequence switch spring 331, left-hand armature and front contact of relay 332, conductor 334, outer right-hand armature and front contact of relay 307, conductor 368, left-hand armature and front contact of relay 263, outer left-hand armature and front contact of relay 259, to ground. The completion of this circuit moves sequence switch 300 out of position 12 and into position 13. When sequence switch 300 leaves position 12, the locking circuit of relay 307 is broken and this relay deenergizes.

In position 13 of sequence switch 300, a circuit is completed from grounded battery,

lower left-hand contact of sequence switch spring 319, winding of stepping relay 320, armature and back contact of relay 321, inner left-hand armature and front contact of relay 306, upper contacts of sequence switch spring 348, resistance 322, upper left-hand contact of sequence switch spring 312, to ground. Stepping relay 320 is now energized by a magnetic field of such polarity that upon release any residual magnetism will be in a direction to aid that normally set up by completion of the fundamental selecting circuit, and upon energization completes a circuit from grounded battery, power magnet of sequence switch 300, lower left-hand contact of sequence switch spring 331, conductors 352 and 310, armature and front contact of relay 320, upper right-hand contact of sequence switch spring 312, to ground, for moving sequence switch 300 out of position 13 and into position 14.

In position 14 of sequence switch 300, circuits are completed to control the selection of talking battery in accordance with the position of class register sequence switch 200. This is accomplished by varying the ratio of the coils in the repeating coil shown in Fig. 2, in accordance with the amount of loading required to produce proper transmission for the type of connection which has been set up. The position of sequence switch 100 will determine the manner in which the various windings of the repeating coil are connected, as will be apparent hereinafter.

To accomplish the selection of talking battery the sequence switch 100 is caused to rotate through various positions and while rotating sends revertive impulses into the sender circuit to control counting relays operated in accordance with the setting of sequence switch 200. This is accomplished in the following manner.

With sequence switch 300 in position 14 of its second revolution, a circuit is completed from grounded battery, left-hand winding of relay 107, lower left-hand and upper right-hand contacts of sequence switch spring 112, inner right-hand armature and front contact of relay 121, sender selector brush 132 and its associated contact, conductor 133, outer right-hand armature and front contact of relay 239, conductor 267, lower left-hand contact of sequence switch spring 318, winding of stepping relay 320, armature and back contact of relay 321, inner left-hand armature and front contact of relay 306, upper contacts of sequence switch spring 348, resistance 322, conductor 369, lower contacts of sequence switch spring 370, right-hand armature and front contact of relay 357, conductor 371 (Figs. 3 and 4), side-switch brush 581 and its associated ninth terminal, conductor 582, right-hand armature and back contact of relay 218, to

ground. Relay 107 and stepping relay 320 are energized in this circuit. Relay 107, upon energization completes a circuit from grounded battery, power magnet of sequence switch 100, lower left-hand contact of sequence switch spring 116, inner right-hand armature and front contact of relay 107, lower contact of sequence switch spring 117, to ground, for moving this sequence switch 5 out of position 11 and into a position to be determined by the counting relays. Relay 107 completes a locking circuit for itself by way of its left-hand armature and front contact, conductors 110 and 111, and the 10 upper contacts of sequence switch spring 112 to ground over the path described. The energization of stepping relay 320 completes a circuit from grounded battery, winding of the zero counting relay, upper left-hand 15 contact of sequence switch spring 268 (Fig. 3), conductor 269, outer right-hand armature and back contact of relay 372, outer right-hand armature and back contact of relay 373, outer right-hand armature and 20 back contact of relay 374, conductor 375, lower contacts of sequence switch spring 363, conductor 394, inner right-hand armature and front contact of relay 306, outer left-hand armature and back contact of relay 307, outer left-hand armature and back 25 contact of relay 308, upper left-hand contact of sequence switch spring 309, armature and front contact of relay 320, upper right-hand contact of sequence switch spring 312, to ground. The zero counting relay is 30 energized in this circuit and prepares a circuit for the zero prime counting relay.

When sequence switch 100 reaches position 11½, a circuit is momentarily closed 40 from grounded battery, left-hand winding of relay 107, left-hand armature and front contact of relay 107, conductors 110 and 111, left-hand contacts of sequence switch spring 145, to ground. Stepping relay 320 is 45 shunted down in this circuit and allows the zero prime counting relay, in parallel with relay 321, to be energized in the well-known manner. Relay 321 upon energization opens the lower branch of the circuit of relay 107 50 and when sequence switch 100 leaves position 11½, the upper branch of the holding circuit of relay 107 is broken and this relay deenergizes, opening the driving circuit of sequence switch 100 and causing this sequence switch to come to rest when it 55 reaches position 12.

During the selection of talking battery, the holding circuit of relay 121 is no longer controlled at the inner left-hand armature 60 and front contact of relay 102, since the sequence switch 100 has left position 11. Due to the energization of relay 107, a substitute holding circuit, however, now extends by way of the upper right-hand contact of 65 sequence switch spring 140, conductor 141,

the outer right-hand armature and front contact of relay 121, the upper right-hand contact of sequence switch spring 142, the outer left-hand armature and front contact of relay 107, conductor 157, lower right-hand and upper left-hand contacts of sequence switch spring 145, to ground. When talking selection is completed and relay 107 deenergizes, as previously described, relay 121 is deenergized and at its inner left-hand 70 armature removes ground from the terminal associated with test brush 115, so that the sender is now selectable by other sender selectors. The removal of ground from test conductor 205 allows relays 207 and 202 to 75 become deenergized. A circuit is then completed from grounded battery, winding of side-switch stepping magnet 520 (Fig. 4), conductor 521, left-hand armature and back contact of relay 503, side-switch brush 522 80 and its associated ninth terminal, conductor 583, outer right-hand armature and back contact of relay 202, to ground. Magnet 520 is energized and advances the side-switch into its tenth position. 85

With the side-switch in position 10, a circuit is completed from grounded battery, winding of the power magnet of sequence switch 200, lower left-hand contact of sequence switch spring 219, conductor 270, side-switch brush 581 and its tenth contact, conductor 582, right-hand armature and back contact of relay 218, to ground. The completion of this circuit moves sequence switch 200 out of position 7 and into 90 position 16. When sequence switch 200 leaves position 15, relays 239, 263, and 259 are deenergized.

In position 16 of sequence switch 200, the operating winding of relay 502 is shunted 95 down due to the closure of a circuit from grounded battery, conductor 584, lower left-hand and upper right-hand contacts of sequence switch spring 220, conductors 271 and 270, side-switch brush 581 and its associated contact, conductor 582, right-hand armature and back contact of relay 218, to ground. Relay 502 is deenergized, causing in turn the deenergization of relay 543. As soon as relay 502 is deenergized, a circuit is 100 completed from grounded battery, power magnet of sequence switch 200, lower right-hand contact of sequence switch spring 219, conductor 272, inner right-hand armature and back contact of relay 502, conductors 110 538 and 273, upper left-hand contact of sequence switch 274, to ground, for moving sequence switch 200 out of position 16 and into position 17.

Referring now to Fig. 6, it should be 125 noted that the locking circuit for relays 306 and 332 is broken as soon as sequence switch 200 leaves position 15. The deenergization of relay 306 causes in turn the deenergization of relays 317 and 357. 130

The deenergization of relay 543 above described completes a circuit from grounded battery, power magnet of sequence switch 300, lower right-hand contact of sequence switch spring 313, conductor 376, inner left-hand armature and back contact of relay 543 to ground, for moving sequence switch 300 out of position 14 and into position 1.

In position 17 of sequence switch 200, 10 with the side switch of Fig. 4 in position 10, circuits are completed for restoring the registers. The units register is the first to be restored in a circuit extending from grounded battery, winding of slow-release 15 relay 503, conductors 523 and 524, winding of units register stepping magnet 535, armature and back contact of magnet 535, register brush 512 and an off-normal contact, stations register brush 511 and its normal 20 contact, conductor 221, right-hand contacts of sequence switch spring 220, conductors 271 and 270, side-switch brush 581 and its associated contact, conductor 582, right-hand armature and back contact of relay 25 218, to ground. Relay 503 and magnet 535 are energized. Magnet 535 interrupts its own circuit until the units register has advanced into its normal position, at which time, no further circuit being found for 30 magnet 535, this magnet remains deenergized with the units register in its normal position.

The tens register is next to be restored. A self-interrupting circuit for its stepping 35 magnet is completed from grounded battery, resistance 504, winding of slow-release relay 503, conductors 523 and 524, winding of tens register stepping magnet 534, armature and back contact of magnet 534, tens 40 register brush 513 and an off-normal contact, thence through units register brush 512 and its normal contact and stations register brush 511 and its normal contact to conductor 221, and then to ground over the 45 path described. Under the control of magnet 534, the tens register is restored to its normal position.

The hundreds, thousands, B and A registers are restored in substantially the same 50 manner, which it is thought will be obvious without further description.

It is to be observed that the translator switch does not have a normal position, but will remain in the position to which it was 55 last set until put into re-operation.

As soon as the registers are completely 60 restored, a circuit is completed from grounded battery, winding of side-switch stepping magnet 520, armature and back 65 contact of relay 520, conductor 521, left-hand armature and back contact of relay 503, side-switch brush 522 and its tenth off-normal contact, conductor 585, A register brush 517 and its normal contact, B register brush 516 and its normal contact, and

thence through brushes 515, 514, 513, 512 and 511 and the normal contacts of the thousands, hundreds, tens, units and stations registers, respectively, in series, to conductor 221, and then to ground over the path 70 previously described. This circuit energizes magnet 520 which advanced the side-switch into position 11 from whence it is driven to its normal position in a self-interrupting circuit leading through brush 581 to ground 75 at the right-hand armature and back contact of relay 218. The registers and their controlling side switch have now all been restored to their normal positions.

As soon as all the registers are restored 80 and their controlling side switch reaches its normal position, a circuit is completed from grounded battery, power magnet of sequence switch 200, upper left-hand contact of sequence switch spring 219, conductor 275, 85 side switch brush 581 and its normal contact, conductor 582, right-hand armature and back contact of relay 218 to ground. The completion of this circuit moves sequence switch 200 out of position 17 and 90 into position 18.

In position 18 of sequence switch 200, circuits are completed for restoring the impulse sequence switch 400, (Fig. 7) which it will be remembered came to rest in position 13 after furnishing a time interval before the dial tone was supplied to the calling subscriber, after he had removed his receiver from the switchhook.

Referring to Fig. 7, a circuit is completed 100 from grounded battery, power magnet of sequence switch 400, upper right-hand contact of sequence switch spring 405, right-hand contacts of sequence switch spring 413, conductors 414 and 596, lower contacts of sequence switch spring 304, conductor 305, inner right-hand armature and back contact of relay 306, outer left-hand armatures and back contacts of relays 307 and 308, lower contact of sequence switch spring 309, 105 and the upper right-hand contact of sequence switch spring 312, to ground. The completion of this circuit moves sequence switch 400 out of position 13 and into position 18, where the circuit just traced is 110 again completed to move sequence switch 400 out of position 18 and into position 1.

When sequence switch 400 reaches position 1, a circuit is completed from grounded battery, power magnet of sequence switch 200, conductor 276 (Figs. 3, 4, 5, 8 and 7), lower right-hand contact of sequence switch spring 405, right-hand contacts of sequence switch spring 413, conductor 414, to ground over the path previously described. The completion of this circuit advances sequence switch 200 out of position 18 and into position 1.

The sender and all of its associated apparatus are now in their normal condition 130

and are ready for reuse upon seizure by another district switch.

When the district selector sequence switch 100 comes to rest in position 12 a circuit is completed from grounded battery, right-hand winding of relay 802 (Fig. 12), left-hand contacts of sequence switch spring 803, resistance 804, conductor 727, terminal 725, brush 724, lower right-hand contact of sequence switch spring 728, conductor 704, terminal 153, brush 154, right-hand contacts of sequence switch spring 155, upper right-hand winding of repeating coil 162, upper contacts of sequence switch spring 163, winding of polarized relay 160, upper left-hand contact of sequence switch spring 161, lower right-hand winding of repeating coil 162, left-hand contacts of sequence switch spring 151, brush 157, terminal 158, conductor 159, lower right-hand contact of sequence switch spring 729, brush 722, terminal 726, conductor 723, upper left-hand contact of sequence switch spring 836 to ground. Relay 802 is energized in this circuit but the direction of current flow is such as not to allow polarized relay 160 to become energized at this time.

It is obvious from an inspection of Fig. 2, that if sequence switch 100 had been brought to rest in position 13, all the windings of the right-hand side of the repeating coil 162 would have been brought into service. It is also obviously within the scope of my invention to provide as many branches and sectional windings for the secondary winding of the repeating coil as may be desired, and that the sequence switch 100 could be arranged to control the cutting-in of any desired number of these windings to produce any one of a number of ratios of secondary turns to primary turns.

If the sequence switch is advanced into position 15 the repeating coil is entirely eliminated as may readily be seen from the drawing, circuits being completed directly to the tip and ring conductors 154 and 155 by way of the upper right-hand contacts of sequence switch springs 128 and 125, respectively.

50 Relay 802, upon energization locks up by way of its right-hand armature and front contact, and conductor 809 to ground, by way of the upper right-hand and lower left-hand contacts of sequence switch spring 837.

55 The energization of relay 802 also completes a circuit from grounded battery, lower left-hand contact of sequence switch spring 805, resistance 806, conductors 838 and 844, upper contacts of sequence switch spring 845, commutator 843, commutator brush 842 to ground. Relay 802 is energized in this circuit and locks up through its inner upper

armature and front contact, and at the same time completes a circuit from grounded battery, power magnet of sequence switch 800, upper right-hand contact of sequence switch spring 816, outer lower armature and front contact of relay 840 to ground. The completion of this latter circuit moves switch 800 out of position 10 and into position 13.

The incoming selector switch is arranged for semi-selective ringing on party lines, that is on a four party line, 2 stations will be signalled over the tip side of the line, and 2 stations will be signalled over the ring side of the line. Further differentiation is completed by a characteristic number of rings, which will be for example, one ring on the tip for subscriber No. 1, and two rings on the tip for subscriber No. 2. One ring on the ring side of the line will signal party No. 3, while two rings on the ring side of the line will signal party No. 4. Transposition of the terminals in the various final switches will determine on which side of the line ringing current will be applied on the principle of the well-known terminal per station arrangement. The stations on the party line are numbered in such a manner that the group in which the final switches which serve such lines appear at the incoming switch will determine whether or not one or two rings are applied to the line.

In the present case, a trunk in the fourth group of trunks served by the third brush on the incoming switch has been seized, and therefore commutator brush 842 will be in engagement with a conducting segment of commutator 843. Commutator brush 842 is arranged to be in engagement with a conducting portion of commutator 843 whenever a trunk in the second or fourth groups has been seized, but will be in engagement with an insulating portion of commutator 843 whenever trunks in the first and third groups have been seized.

Under the above assumptions relay 840 will be shunted down as soon as sequence switch 800 reaches position 11 $\frac{3}{4}$ by a circuit extending from grounded battery, lower left-hand contact of sequence switch spring 805, resistance 806, conductors 838 and 844, upper contacts of sequence switch spring 845, commutator 843, commutator brush 842 to ground.

If brush 842 had not been in engagement with commutator 843, one ring would have been applied to the line as soon as sequence switch 800 comes to rest in position 13, due to the fact that relay 840 had not been released.

Under the present assumption, however, when sequence switch 800 reaches position 13, since relay 840 is deenergized, no current is applied to the line and sequence switch 800 is immediately moved out of position 13.

13 due to the completion of a circuit from grounded battery, power magnet of sequence switch 800, lower right-hand and upper left-hand contacts of sequence switch spring 845, commutator 843, brush 842 to ground. The completion of this circuit moves sequence switch 800 into position 14.

The advance of sequence switch 800 out of position 14 is dependent on the operation of pick-up interrupter 846, the action of which insures that in case two rings are to be applied to the line, a complete cycle of ringing operations will take place, thus avoiding the possibility of applying only one ring or a partial or mutilated first ring. When contact is made by interrupter 846, a circuit is completed from grounded battery, lower left-hand contact of sequence switch spring 805, resistance 806, conductor 838, right-hand armature and back contact of relay 839, winding of relay 840, upper contacts of sequence switch spring 841, outer upper armature and back contact of relay 840, lower left-hand contact of sequence switch spring 847, a conducting segment and brush of pick-up interrupter 846 to ground. Relay 840 energizes in this circuit and locks itself to ground at the left-hand armature and front contact of relay 802 as previously described. Relay 840 upon energization also completes a circuit from grounded battery, power magnet of sequence switch 800, upper right-hand contact of sequence switch spring 816, outer lower armature and front contact of relay 840, to ground, to move sequence switch 800 out of position 14 and into position 15.

In position 15, two rings are applied to the called line from ground through a suitable source of ringing current of any desired type (not shown) and controlled by a suitable interrupter (not shown), this apparatus being generally indicated at 848, thence through the lower left-hand contact of sequence switch spring 849, winding of relay 839, inner lower armature and front contact of relay 840, upper left-hand contact of sequence switch spring 833, brush 827, terminal 828, conductor 829, lower right-hand contact of sequence switch spring 943, brush 965, terminal 946, conductor 947, thence over the called line, including the bell at the wanted substation, to ground. Relay 839 is not energized in this circuit, but awaits the response of the called subscriber. When the called subscriber answers, the circuit of relay 839 extends to the called substation by way of the path previously described, and returns by way of line conductor 948, terminal 949, brush 950, upper contacts of sequence switch spring 914, conductor 832, terminal 831, brush 830, lower right-hand and upper left-hand contacts of sequence switch spring 841, and the outer upper armature and front con-

tact of relay 840 to ground. Relay 839 is energized in this circuit and completes a circuit from grounded battery, right-hand winding of relay 850, left-hand armature and front contact of relay 839 to ground, and at its right-hand armature opens the locking circuit of relay 840 which deenergizes and removes the ringing current from the called line and at the same time establishes the talking connection through the incoming switch. Relay 850 is energized in the circuit above traced and locks up through its right-hand armature and front contact, the upper left-hand contact of sequence switch spring 851 to the ring conductor 723, thence over the path previously traced through repeating coil 162, returning by way of tip conductor 727 through the upper left-hand contact of sequence switch spring 852, and left-hand winding of relay 850 to ground. Relay 850 remains energized in this circuit and supplies talking battery to the called subscriber. It is to be observed also that the current flow in the circuit above traced is now in a direction to energize polarized relay 160, (Fig. 2).

The energization of relay 160 completes a circuit from grounded battery, winding of charge relay 152, right-hand contacts of sequence switch spring 109, conductor 164, armature and front contact of relay 160, upper right-hand contact of sequence switch spring 166 to ground. Relay 152 is energized in this circuit and locks up through the upper contacts of sequence switch spring 109 and its outer right-hand armature and front contact to ground, until sequence switch 100 leaves position 18.

The connection is now completed and the subscribers may converse. It should be noted that the talking conductors of the calling subscriber's line were connected through to the left-hand windings of repeating coil 162, as soon as sequence switch 100 reached position 11, and remain so connected in position 12 of sequence switch 100. Battery is supplied to the calling subscriber's line through the windings of the repeating coil. A supervisory relay 167 is included and energized in this circuit.

It would be well to observe at this point that relay 139 is a differentially wound relay and is maintained energized in positions 2 to 11 of sequence switch 100 by a circuit from grounded battery, left-hand winding of relay 139, upper left-hand contact of sequence switch spring 122 to ground. In positions 1 to 10 of sequence switch 100, a circuit is in existence through the right-hand winding of relay 139, but since this circuit includes a resistance 243 in Fig. 3, the magnetism set up in the right-hand winding of relay 139, is not sufficient to overcome the polarity of that set up in the left-hand wind-

ing and therefore, relay 139 remains energized. When sequence switch 100 reaches position 10½, supervisory relay 167 is energized and the holding circuit of relay 139 now extends through its left-hand winding, the armature and front contact of relay 167, and the right-hand armature and front contact of relay 139 to ground. As soon as sequence switch 100 leaves position 11, the circuit of the left-hand winding of relay 139 is entirely dependent on the relay 167.

When the conversation is completed and connection is no longer desired, the calling subscriber will replace his receiver, causing the deenergization of relay 167, which causes in turn the deenergization of relay 139. A circuit is thereupon completed from grounded battery, power magnet of sequence switch 100, conductor 168, lower right-hand and upper left-hand contacts of sequence switch spring 169, right-hand armature and back contact of relay 139 to ground, for moving sequence switch 100 out of position 12 and into position 17. The deenergization of relay 139 does not allow relay 102 to deenergize since this relay is maintained energized in a holding circuit through its right-hand winding, by way of conductor 170, the left-hand armature and front contact of relay 152, conductor 171, the upper left-hand contact of sequence switch spring 103 to ground through the cut-off relay and message register of the calling subscriber's line.

In position 17, due to the energized condition of charge relay 152, a circuit is completed from grounded battery, right-hand contacts of sequence switch spring 172, outer left-hand armature and front contact of relay 102, the left-hand non-inductive winding of relay 102, conductor 170 to ground over the path described. The battery supplied through the two windings of relay 102 in parallel raises the potential of conductor 171 sufficiently to allow the message register magnet 17 to operate and lock up to record a call against the calling subscriber. It is obvious that if the called subscriber had not answered, charge relay 152 would not have operated and no charge would have been made against the calling subscriber.

In position 17 of sequence switch 100, a time interval is provided by way of interrupters indicated at 173 and 174 to insure the allowance of enough time for the proper operation of the register operating magnet. As soon as a circuit is completed through the conducting segments of interrupter 173, a circuit is completed from grounded battery, right-hand winding of relay 107, lower left-hand contact of sequence switch spring 108, conducting segments of interrupter 173 to ground. Relay 107 is energized in this circuit and locks up through its left-hand armature to ground by way of conductors

110 and 111, and left-hand contacts of sequence switch spring 145. When shortly thereafter interrupter 174 completes a circuit through its contacts, a circuit is completed from grounded battery, left-hand winding of relay 139, conductor 175, upper contacts of sequence switch spring 142, outer right-hand armature and front contact of relay 107, conductor 176, right-hand contacts of sequence switch spring 177, contacts of interrupter 174 to ground. Relay 139 is energized in this circuit and completes a circuit from grounded battery, power magnet of sequence switch 100, lower right-hand contact of sequence switch spring 116, inner right-hand armature and front contact of relay 107, upper right-hand contact of sequence switch spring 117, right-hand armature and front contact of relay 139 to ground for moving sequence switch 100 out of position 17 and into position 18.

In case the call had been unsuccessful and the calling subscriber had received no answer, charge relay 152 would not have been operated. Therefore when the calling subscriber replaced his receiver on the hook, relay 139 would have been deenergized and have caused sequence switch 100 to move into position 17 as previously described. In this case, however, the deenergization of relay 139 would have caused the deenergization of relay 102 as soon as relay 139 deenergized, since with charge relay 152 deenergized, no holding circuit for relay 102 is in existence. Sequence switch 100 would therefore immediately move out of position 17 and into position 18, due to the closure of a circuit from grounded battery, power magnet of sequence switch 100, conductor 168, lower contacts of sequence switch spring 169, right-hand armature and back contact of relay 102 to ground.

In position 18 of sequence switch 100, a circuit is completed from grounded battery, winding of down drive magnet 178, upper contacts of sequence switch spring 169, right-hand armature and back contact of relay 139 to ground. Under the control of magnet 178, the district brush shaft is returned to its normal position and when its normal position is reached a circuit is completed from grounded battery, power magnet of sequence switch 100, lower left-hand contact of sequence switch spring 116, normal commutator segment 179, commutator brush 180 to ground, for moving sequence switch 100 out of position 18 and into position 1.

As soon as sequence switch 100 leaves position 17, the battery supply on the sleeve terminal of the line switch is cut off and the cut-off relay of the calling line is deenergized to allow the calling subscriber's line switch to be restored to its normal position. The deenergization of relay 102 also removes

the busy ground condition from the test terminal of the line switch to render the district switch selectable by other hunting line switches.

- 5 Referring now to Fig. 9, it will be observed that during talking, which takes place in position 8 of sequence switch 700, relay 702 is locked up to conductor 720, which is supplied with ground from the district selector switch. Similarly, referring to Fig. 12, in the talking position of the incoming selector switch, which is position 15 of sequence switch 800, relay 802 is locked up through its right-hand armature and the 10 upper right-hand contact of sequence switch spring 837 to conductor 728, which is also supplied with ground from the district switch by way of conductor 720. It is therefore obvious that when sequence switch 15 20 moves out of position 14½, removal of ground from conductor 720, will allow relays 702 and 802 to deenergize.

The deenergization of relay 702 completes a circuit from grounded battery, power magnet of sequence switch 700, lower left-hand contact of sequence switch spring 711, left-hand armature and back contact of relay 702 to ground, for moving sequence switch 700 out of position 8 and into position 18.

In position 18 of sequence switch 700, a circuit is completed from grounded battery, winding of down-drive magnet 730, upper right-hand and lower left-hand contacts of sequence switch spring 731 to ground. The selector brush shaft is returned to its normal position under the control of magnet 730 and when its normal position is reached a circuit is completed from grounded battery, power magnet of sequence switch 700, lower right-hand contact of sequence switch spring 711, normal commutator segment 732, commutator brush 733 to ground, for moving sequence switch 700 out of position 18 and into position 1.

At the incoming selector switch, the deenergization of relay 802 completes a circuit from grounded battery, winding of power magnet of sequence switch 800, the lower right-hand contact of sequence switch spring 816, the left-hand armature and back contact of relay 802 to ground, for moving sequence switch 800 out of position 15 and into position 18.

In position 18 of sequence switch 800, a circuit is completed from grounded battery, winding of down-drive magnet 853, upper contact of sequence switch spring 854 to ground. The incoming selector switch 55 brush shaft is returned to its normal position under the control of magnet 853, and when it reaches its normal position a circuit is completed from grounded battery, power magnet of sequence switch 800, upper left-hand contact of sequence switch spring 816,

normal commutator segment 855, commutator brush 823 to ground, for moving sequence switch 800 out of position 18 and into position 1.

As soon as sequence switch 800 leaves position 15½ the ground which has been holding relay 915 (Fig. 13) energized, is removed and relay 915 deenergizes. A circuit is then completed from grounded battery, left-hand winding of relay 912, upper right-hand and lower left-hand contacts of sequence switch spring 903, right-hand armature and back contact of relay 915 to ground. Relay 912 is energized and at its left-hand armature and front contact completes a circuit from grounded battery, power magnet of sequence switch 900, upper left-hand contact of sequence switch spring 922, left-hand armature and front contact of relay 912 to ground, for moving sequence switch 900 out of position 15 and into position 16.

Provided that the called subscriber has not replaced his receiver up to this time, relay 912, upon energization locks up through its right-hand armature and front contact by way of conductor 953, the right-hand contacts of sequence switch spring 943, brush 965, terminal 946, conductor 947, thence through the substation apparatus of the called substation, returning by way of conductor 948, terminal 949, brush 950, conductor 954 and the lower right-hand contact of sequence switch spring 910 to ground. The release of the final connector switch is now under control of the called subscriber. When he replaces his receiver, relay 912 deenergizes and completes a circuit from grounded battery, power magnet of sequence switch 900, upper right-hand contact of sequence switch 922, left-hand armature and back contact of relay 912 to ground, for moving this sequence switch out of position 16 and into position 17 from which position it is immediately moved into position 18, due to the completion of a circuit from grounded battery, power magnet of sequence switch 900, lower left-hand contact of sequence switch spring 917, right-hand armature and back contact of relay 915 to ground.

In position 18 of sequence switch 900 a circuit is completed from grounded battery, winding of down-drive magnet 938, upper right-hand contact of sequence switch spring 919, lower left-hand contact of sequence switch spring 916, to ground. The final selector brush shaft is returned to its normal position under the control of magnet 938 and when it reaches its normal position a circuit is completed from grounded battery, power magnet of sequence switch 900, upper right-hand contact of sequence switch spring 917, normal commutator segment 940, commutator brush 939 to ground, 120 125 130

for moving sequence switch 900 out of position 18 and into position 1. Referring now to Fig. 1, the release of the calling subscriber's individual line switch will be described. As soon as message register magnet 17 is energized due to current flow through the two windings of relay 102 in parallel as previously described, a circuit is completed from ground-
ed battery, winding of stepping magnet 4, armature and back contact of magnet 4, conductor 18, armature and front contact of message register magnet 17, middle lower armature and front contact of cut-off relay 3, and lower winding of cut-off relay 3 to ground. Magnet 4 is energized in this circuit and interrupts its circuit to cause the advance of the line switch. Magnet 4 continues to interrupt its own circuit to advance the line switch into its normal position.

As soon as sequence switch 100 leaves position 17, battery is no longer supplied to conductor 104 and message register magnet 17 and cut-off relay 3 are both deenergized. Stepping magnet 4, however, continues to advance the line switch towards its normal position, due to the completion of a self-interrupting circuit for said magnet extending from grounded battery, winding, armature and back contact of magnet 4 lower-most armature and back contact of cut-off relay 3, right-hand armature and back contact of line relay 2, off-normal contact 13 to ground. When the line switch reaches its normal position, off normal contact 13 is opened and the line switch is brought to rest in readiness for reoperation.

It is to be observed that an additional restoring circuit for the line switch was completed as soon as the message register is operated and that therefore it was not necessary to await the advance of the district sequence switch and the consequent de-energization of cut-off relay 3. This novel arrangement results in a distinct saving of time and allows the calling subscriber to initiate a second call much more quickly than would otherwise be the case.

Referring now to Fig. 14, the operation of the sender monitoring apparatus there disclosed will now be described. It is the function of this apparatus to call to the attention of a special operator, whom we shall call a monitoring operator, various irregularities in the progress of the call. The irregularities which will be called to the attention of the operator are—

(1) Permanent signal.—This is a condition which arises when a subscriber initiates a call and then does not dial and also fails to replace his receiver. This condition is indicated to the monitoring operator by a continuous bright lighting of indicating lamp 19.

(2) When the calling subscriber dials the office code, but does not dial the digits of the wanted number and does not abandon the call. This will be indicated to the operator by a continuous dim lighting of lamp 19.

(3) Stuck sender, that is, when the sender fails to operate properly within a given period of time as evidenced by the remaining of the sender sequence switch in a given position for more than a predetermined length of time. This is indicated to the operator by the flashing of lamp 19.

The first condition, that in which a calling subscriber merely lifts his receiver from the switchhook and does not dial within a predetermined length of time, will first be described.

The operation of the system is identical with that previously described up to the point where line relay 215 is energized, causing in turn the energization of slow-to-release relay 217 and relay 218. It should be borne in mind that the class sequence switch 200 is at this time in position 3 and that the sender control or side switch is in its normal position. The energization of relay 218 completes a circuit from ground, right-hand armature and front contact of relay 218, conductor 537, side switch arm 536 and its normal contact, winding of relay 291 to grounded battery. Relay 291 is energized in this circuit and remains energized.

As soon as sequence switch 200 reaches position 13 $\frac{1}{4}$ a circuit is completed for starting in operation the monitoring device, which includes a time measuring device to control the operation of the signal. The time measuring device consists of a switch which is put into operation under the control of an interrupter to count off a certain period of time before the signals shall be given to the operator. In order to prevent needless operation of this switch a certain number of counting relays are provided which are put into operation before the switch is put off normal, these counting relays also being under the control of an interrupter. Assuming then, that sequence switch 200 has reached position 13 $\frac{1}{4}$ a circuit is completed from grounded battery, winding of relay 23, conductor 32, left-hand armature and back contact of relay 26 through the contacts of a slow operating interrupter 25, outer right-hand armature and back contact of relay 26, armature and back contact of relay 22, conductor 33, outer left-hand armature and back contact of relay 600, conductors 34, 225, 224, outer right-hand armature and back contact of relay 223, conductors 222, 538, and 273 and the upper left-hand contact of sequence switch spring 274 to ground. Counting relay 23 is energized in this circuit and prepares a

locking circuit for itself, including the winding of counting relay 22. Counting relay 22 is however shunted as long as interrupter 25 allows current to pass through its contacts. As soon as the circuit is broken by the action of interrupter 25, relay 22 is energized. The circuit of relays 23 and 22 now extends from grounded battery, winding of relay 23, winding of relay 22, armature and front contact of relay 23, conductor 33 and thence to ground over the path described. Assuming that the condition continues, that is, that the called subscriber does not dial, the monitoring device continues its operation. When the circuit is again completed through the contacts of interrupter 25 a circuit is completed for relay 21 in parallel with relay 22. This circuit extends from grounded battery, winding of relay 23, conductor 32, left-hand armature and back contact of relay 26, contacts of interrupter 25, outer right-hand armature and back contact of relay 26, armature and front contact of relay 22, winding of relay 21, armature and front contact of relay 23, conductor 33 to ground over the path described. The energization of relay 21 allows relay 26 to be operated over a circuit extending from grounded battery, winding of relay 26, inner right-hand armature and back contact of relay 35, right-hand armature and front contact of relay 21, conductor 33 to ground as described. The energization of relay 26 puts the step-by-step monitoring switch, which is of similar mechanical construction to the register switches, into operation. The monitoring switch comprises three contact arms 28, 29 and 30 with their respective contact banks and is controlled by stepping magnet 27. The advance of the monitoring switch is now under the control of interrupter 25. The circuit of magnet 27 extends from grounded battery, winding of magnet 27, outer left-hand armature and back contact of relay 35, left-hand armature and front contact of relay 26, interrupter 25, outer right-hand armature and front contact of relay 26, brush 28 and its normal contact to ground. Magnet 27 is energized in this circuit and as soon as interrupter 25 opens this circuit magnet 27 is deenergized to cause the advance of the monitor switch brushes into engagement with their off-normal contacts. The operation of the monitor switch continues until brush 28 engages its eighth off-normal contact, at which time the monitor brush set is brought to rest.

It is to be observed that during the advance of the monitor switch a circuit is in existence through the winding of relay 35 which extends from grounded battery, winding of relay 26, winding of relay 35, arm 29 and off-normal contact to ground. Relay 35 does not energize, however, since it is

shunted by the direct ground applied by way of its inner right-hand armature and back contact, and the right-hand armature and front contact of relay 21 and conductor 33.

Should the subscriber dial before the monitoring switch reaches position 8, the setting of the first two registers with the resultant setting of the translator switch would cause the energization of relay 22. This would open the above traced circuit and remove ground from conductor 33. Ground is supplied to conductor 33, however, until the sender sequence switch 300 has completed its first revolution. This ground is supplied to conductor 34 by way of conductors 225 and 224, the lower left-hand contact of sequence switch spring 390 and conductor 327. The monitoring switch is always put into operation and continues in operation until the proper signal is given to indicate to the monitoring operator the nature of the trouble which is causing the unusual functioning of the apparatus, or until the call has properly passed a certain stage of operation. If at any time, ground is removed from conductor 33 the monitoring device is restored to its normal position before giving any signal. If the ground is removed before all the relays have operated the relays are merely unlocked and returned to their normal position. If ground is removed from conductor 33 after the switch has been put into operation the removal of ground from conductor 33 allows relay 35 to be energized. The energization of relay 35 completes a circuit from grounded battery, winding of magnet 27, armature and back contact of magnet 27, inner left-hand armature and front contact of relay 35, inner right-hand armature and front contact of relay 26, which remains energized in series with relay 35, conductor 36, arm 29 and some off-normal contact to ground. Magnet 27 operates in this self-interrupting circuit until the monitoring switch reaches its normal position at which time arm 29 engages an ungrounded contact, as a result of which relays 35 and 26 are also allowed to be de-energized.

If the cause of the continued grounding of conductor 33 is the fact that the subscriber has not dialed at all, relay 291 will be energized as previously described. When monitoring brush 30 reaches its eighth off-normal contact, a circuit is completed from grounded battery, lamp 19, arm 30 and its associated contact, outer left-hand armature and back contact of relay 35, conductor 37, armature and back contact of relay 292, right-hand armature and front contact of relay 291 to ground. Lamp 19 is caused to burn brightly in this circuit since it is a circuit extending directly to ground through no resistance. The con-

tinuous bright lighting of lamp 19 informs the operator that the subscriber has initiated a call and then failed to dial.

When the operator observes the continuous lighting of lamp 19 she inserts a plug in make busy jack 38. The sleeve contact of this jack is connected to ground and a circuit is therefore completed from said ground, through the sleeve contact of jack 38, conductor 39, and the right-hand winding of relay 206 to grounded battery. Relay 206 is energized and at its outer right-hand armature and front contact supplies ground to conductor 205 to make the sender busy and nonselectable to any other district switch. The operator also inserts a plug into jack 31. The sleeve of the plug which is inserted in the jack 31 is connected to battery, and as a result, the circuit is completed for energizing relay 600. Relay 600 upon energization completes a holding circuit for line relay 215 extending from grounded battery, winding of line relay 215, conductor 216, right-hand winding of relay 600, right-hand armature and operated contacts of relay 600, conductor 602, and the right-hand winding of coil 213 to ground. Relay 600 is locked up in this circuit. At its outer left-hand armature relay 600 removes ground from conductor 33, and the monitor switch is restored to its normal condition. The operator may now insert the plug of a monitoring cord circuit of any well-known design, such for example, as disclosed in the Patent No. 1,509,851, issued to E. F. Trapp September 30, 1924, in jack 31 and therewith notify a subscriber of the condition of a receiver off the hook and she may also instruct a calling subscriber as to the proper operation of the substation dial.

If the subscriber had dialed the office code but has not dialed any of the digits in the wanted number, the system will operate as previously described, the A and B registers will be set and the translator switch will be positioned in accordance with their joint settings. The sender will then operate to accomplish district and office selections and come to rest in position 9 awaiting further dialing by the calling subscriber. If he does not dial within a predetermined interval, the monitoring switch (which started in operation as soon as sequence switch 200 reached position 3), will continue in operation and reach its eighth off-normal position. At this time, lamp 19 will be caused to burn dimly due to circuit conditions which will now be described.

Relay 291 was initially energized as previously described, but as soon as the subscriber dialed the first series of impulses side switch arm 586 leaves its normal contact, and therefore relay 291 is deenergized. The circuit of lamp 19 therefore, will at this time, extend from grounded battery,

lamp 19, monitor switch arm 30 and its eighth off-normal contact, outer right-hand armature and back contact of relay 35, conductor 37, winding of relay 292, conductor 293, upper contact of sequence switch spring 391, conductor 392, outer left-hand armature and front contact of relay 218 to ground. Relay 292 is energized in this circuit and attracts its armature and remains energized until the monitoring switch is restored. The resistance of relay 292 is sufficient to prevent lamp 19 from burning brightly. The operator upon observing the lighting of lamp 19 proceeds as before by inserting plugs into jacks 38 and 31, and getting in touch with the calling subscriber.

If the calling subscriber dials the number completely and the system fails to operate correctly, either due to failure of switches or failure of the sender, this will be evidenced by the fact that the sender sequence switch 300 will not properly advance from position to position, but will remain in whatever position it was at the time the difficulty arose. Ground therefore will be supplied to conductor 34 by way of conductors 225 and 224, and the lower right-hand contact of sequence switch spring 390, to ground at sequence switch spring 312. Normally, the monitoring switch will advance until the sender sequence switch has completed its first revolution, and at this time the monitoring switch will be restored. When the sender switch 300 starts on its second revolution the monitoring switch is again put into operation and continues until restored, due to the fact that sequence switch 200 is restored after the call has been successfully put through.

If the trouble to be indicated to the monitoring operator is due to the fact that the sender has failed to advance, it is obvious that relay 291 will not be energized since the side switch has left its normal position. It is also obvious that relay 292 cannot be energized due to the fact that sequence switch 300 is not in position 9. The circuit of lamp 19 therefore, extends from grounded battery, lamp 19, monitor brush 30 and its eighth off-normal contact, outer right-hand armature and back contact of relay 35, conductor 37, armature and back contact of relay 292, armature and back contact of relay 291, conductor 294, contacts of interrupter 24 to ground. Lamp 19 is caused to flash under the control of interrupter 24, and advises the operator as to the nature of the difficulty. In this case she gets in touch with the calling subscriber as previously described, and advises him that some difficulty has been encountered, and that he must replace his receiver and initiate a new call. When the calling subscriber replaces his receiver the apparatus is restored in the following manner.

It will first be assumed that at the time the calling subscriber replaces his receiver the district switch has completed its selective operations. Sequence switch 100 will therefore, be in position 10. After the monitoring operator has conversed with the calling subscriber she removes her plug from jack 31, which again places line relay 215 under the control of the calling subscriber. The calling subscriber's replacement of his receiver therefore, causes the de-energization of line relay 215 and the consequent deenergization of relays 217 and 218. The deenergization of relays 217 and 218 allows relay 259 to be energized by means of a circuit extending from grounded battery, winding of relay 259, conductor 265, right-hand contacts of sequence switch spring 266, inner left-hand armature and back contact of relay 218, armature and back contact of relay 215 to ground. Relay 259 is energized and locks up through its inner left-hand armature and front contact to ground by way of the upper right-hand contact of sequence switch spring 238. As a result of the energization of relay 259 direct ground is supplied to the left-hand winding of relay 139, this circuit extending from grounded battery, right-hand winding of relay 139, upper left-hand contact of sequence switch spring 140, outer right-hand armature and front contact of relay 121, lower right-hand contact of sequence switch spring 142, sender selector brush 143 and its associated contact, conductor 144, outer left-hand armature and back contact of relay 239, conductor 242, left-hand armature and back contact of relay 263, outer left-hand armature and front contact of relay 259 to ground. Since relay 139 is a differential relay and since it has been energized by a circuit through its left-hand winding, the result of the increased current flow through its right-hand winding allows this relay to release.

Relay 139 upon deenergization opens at its left-hand armature the holding circuit of relay 102 and cut-off relay 3, and these relays are therefore, deenergized. The de-energization of cut-off relay 3 causes the release of the subscriber's individual line switch as previously described, and he is now free to initiate a new call.

The monitoring operator then takes steps to have a trouble man investigate the nature of the trouble which caused the incorrect operation of the sender.

The manner in which the apparatus is restored to its normal condition in case the calling subscriber prematurely abandons his call, that is, replaces his receiver before the connection is complete, will now be described.

The replacing of the receiver by the calling subscriber will in every case result in

the deenergization of differential relay 139 and the consequent deenergization of relay 102 and cut-off relay 3 as just described, so that the line switch is immediately restored in every case.

It will first be assumed that the district switch has been positioned at the time the calling subscriber replaces his receiver. In this case the district sequence switch is in position 10.

If the sequence switch 100 had been in some position other than awaiting the completion of selections beyond, the deenergization of relay 139 would complete circuits for restoring the district switch immediately. However, in order to prevent the possibility of failure to release the succeeding switches in the train, it is necessary to wait until all such switches have been set before the district switch can be released. Sequence switch 100 does not move out of position 10 since it cannot advance until relay 107 is de-energized, this relay being maintained energized by means of a circuit completed at the right-hand armature and front contact of relay 152, which, it will be remembered, is at this time, held energized by means of ground supplied to conductor 144.

In case the subscriber has dialed his complete code at the time of replacing his receiver, all of the switches are set as previously described, and sequence switch 100 is moved out of position 10 and into position 11 as previously described. As soon as the sender circuits arrive at a condition to accomplish talking selection in the district, sequence switch 100 is moved out of position 11 as previously described. However, since the subscriber has abandoned the call a circuit is completed as soon as sequence switch 100 reaches position 12, this circuit extending from grounded battery, power magnet 100, conductor 168, lower right-hand and upper left-hand contacts of sequence switch spring 169, right-hand armature and back contact of relay 139 to ground for advancing sequence switch 100 out of position 12 and into position 17.

Since relay 102 is deenergized as soon as relay 139 is deenergized, sequence switch 100 is immediately moved out of position 17 and into position 18 due to the completion of a circuit extending from grounded battery, winding of power magnet of sequence switch 100, conductor 168, lower contacts of sequence switch spring 169, right-hand armature and back contact of relay 102 to ground. The completion of this circuit causes the advance of sequence switch 100 out of position 17 and into position 18. The district selector is then restored to its normal position as previously described. The office, incoming, and final selector switches are also restored in a manner identical with that previously described.

In case the calling subscriber abandons the call without having fully dialed the digits of the wanted number, and assuming that the district switch has been positioned at the time such abandonment takes place, the release of the apparatus is accomplished in a manner substantially like that described. As before, relay 139 is deenergized and causes the deenergization of relay 102 and 10 cut-off relay 3 with the subsequent restoration of the line switch. The office, incoming, and final selectors are operated in turn, but since the registers have not been positioned, they will take zero settings since in the normal position of the registers they will control the counting relays to send one impulse only in each case, as may readily be observed from a study of the drawings.

If the calling subscriber abandons the call 20 before the district switch has been positioned, the release of the district switch may be accomplished in one of several ways depending upon the particular position in which sequence switch 100 is resting at the 25 time of the abandonment of the call. In each case, relays 139, 102 and 3 will be deenergized as previously described.

If sequence switch 100 has not yet reached position 7 at the time of abandonment of the 30 call, the deenergization of relay 102 completes a circuit from grounded battery, winding of power magnet of sequence switch 100, conductor 168, lower contacts of sequence switch spring 169, right-hand armature and back contact of relay 102 to ground, for moving sequence switch 100 out of whatever position it is in and into position 7. In 35 position 7, with relay 102 deenergized, a circuit is completed from grounded battery, 40 winding of down drive magnet 178, upper right-hand and lower left-hand contacts of sequence switch spring 169, right-hand armature and back contact of relay 102 to ground. The district selector brush 45 shaft is then restored to its normal position, and when it reaches its normal position a circuit is completed from grounded battery, power magnet of sequence switch 100, lower left-hand contact of sequence 50 switch spring 116, normal commutator segment 179 and commutator brush 180 to ground, for moving sequence switch 100 out of position 7 and into position 1.

If sequence switch 100 is standing in position 55 7 at the time the subscriber abandons the call the deenergization of relay 102 will complete the above traced circuits for causing the restoration of the switch by energizing down drive magnet 178, and sequence 60 switch 100 is then advanced in position 1 by means of the normal commutator segment, as just described.

If the calling subscriber abandons the call 65 after sequence switch 100 has left position 7 but before it reaches position 10, the remain-

ing switches in the train are operated. If it is in position 8 trunk hunting is completed and the switches are then positioned as previously described. After all the switches have been set, release takes place in the usual 70 manner.

What is claimed is:

1. In a telephone exchange system, calling and called subscribers' lines, an automatic switch for interconnecting said lines, primary registering devices, means to position said primary registering devices under the control of the calling subscriber, a secondary registering device, means to position said secondary registering device in accordance 75 with the joint setting of certain ones of said primary registering devices, and means to operate said automatic switch under the control of said secondary registering device. 80

2. In a telephone exchange system, calling and called subscribers' lines, an automatic switch for interconnecting said lines, primary registering devices, means to position said primary registering devices under the control of the calling subscriber, a secondary 85 registering device, means to operate said secondary registering device, in a hunting movement to cause it to assume a position determined under the joint control of certain ones of said primary registering devices, and means to operate said automatic switch under the control of said secondary 90 registering device. 95

3. In a telephone exchange system, calling and called subscribers' lines, automatic switches for interconnecting said lines, a plurality of primary registering devices, means to position said primary registering devices under the control of the calling subscriber, a secondary registering device, means to position said secondary registering device in accordance with the joint setting of a plurality of said primary registering devices, and means to operate a plurality 100 of said automatic switches under the control of said secondary registering device. 105

4. In a telephone exchange system, calling and called subscribers' lines, automatic switches for interconnecting said lines, a plurality of primary registering devices, a secondary registering device, means to position said primary registering devices under the control of the calling subscriber, means to position said secondary registering device under the joint control of a plurality of said primary devices, a routing switch, means to position said routing switch in accordance with the position assumed by said secondary registering device, and means to operate said automatic switches under the control of said registering devices and said routing switch. 115

5. In a telephone exchange system, calling and called subscribers' lines, primary 120 registering devices, contacts therefor, means 125

- to position said primary registering devices under the control of the calling subscriber, a secondary registering device, a test circuit for said secondary registering device extending serially through contacts of said primary registering devices, means to position said secondary registering device under the control of said test circuit, and means to operate said automatic switch under the control of said secondary registering device.
6. In a telephone exchange system, calling and called subscribers' lines, automatic switches for interconnecting said lines, a plurality of primary registering devices, a secondary registering device, means to position said primary registering devices under the control of the calling subscriber, means to position said secondary registering device under the joint control of a plurality of said primary registering devices, a routing switch, means to operate said routing switch in a hunting movement to assume a position in accordance with the setting of said secondary registering device, and means to operate said automatic switches under the control of said registering devices and said routing switch.
7. In a telephone exchange system, calling and called subscribers' lines, automatic switches for interconnecting said lines, a plurality of primary registering devices, a secondary registering device, means to position said primary registering device under the control of the calling subscriber, means to position said secondary registering device under the joint control of a plurality of said primary devices, a routing switch, means to position said routing switch in accordance with the position assumed by said secondary registering device, and means to operate said automatic switches under the control of said secondary registering device and said routing switch.
8. In a telephone exchange system, calling and called subscribers' lines, automatic switches for interconnecting said lines, a plurality of primary registering devices, a secondary registering device, means to position said primary registering device under the control of the calling subscriber, means to position said secondary registering device under the joint control of a plurality of said primary registering devices, a routing switch, means to operate said routing switch in a hunting movement to assume a position in accordance with the setting of said secondary registering device, and means to operate said automatic switches under the control of said secondary registering device and said routing switch.
9. In a telephone exchange system, incoming and outgoing lines, link circuits for interconnecting said lines, a plurality of sending devices common to said link circuits, a step-by-step switching device individual to each of said link circuits, and means to operate said switching device to associate an idle sending device with the link circuit to which said switching device is individual.
10. In a telephone system, a subscriber's line, selective switches for extending said line, a plurality of register senders common to said switches for controlling the selective movement thereof, means for connecting the subscriber's line to one of said senders, an operator's position, a signal thereat, a timing device, means to operate said timing device to measure an interval of time to be consumed by said sending device in its normal operation, means to delay the operation of said sending device due to various unstandard conditions, and means to operate said signal under the control of said time measuring device in a distinctive manner to indicate the nature of the unstandard condition.
11. In a telephone system, a subscriber's line, selective switches for extending said line, a plurality of register senders common to said switches for controlling the selective movement thereof, means for connecting the subscriber's line to one of said senders, an operator's position, a signal thereat, means to delay the advance of said sender due to the presence of various unstandard conditions, and means to operate said signal in a discriminating manner to indicate to the operator the nature of the unstandard condition which caused the delay of the sender.
12. In a telephone system a plurality of pieces of apparatus cooperating to complete telephone calls, a timing device and a progressively movable switch for detecting faulty apparatus, said timing device functioning to measure an interval of time equal to the maximum amount of time consumed by said apparatus in its normal operation and thereby preventing said switch from operating except when some of said apparatus is faulty, a signal, and circuits completed by said switch to operate said signal.
13. In a telephone exchange system, a calling subscriber's line, outgoing trunks, an automatic switch, means to operate said automatic switch in response to the initiation of a call to extend said subscriber's line to an idle one of said trunk lines, a toll device associated with said calling subscriber's line, means to operate said toll device, restoring means for said automatic switch, and means to put said restoring means into operation as soon as said toll device is operated.
14. In a telephone exchange system, a calling subscriber's line, outgoing trunks, an automatic switch individual to each subscriber's line, means to operate said auto-

- matic switch to extend said subscriber's line to an idle one of said trunk lines, a toll device associated with said calling subscriber's lines, means to operate said toll device, restoring means for said automatic switch, and means to put said restoring means into operation as soon as said toll device is operated.
15. In a telephone exchange system, a calling subscriber's line, outgoing trunks, an automatic switch, means to operate said automatic switch in response to the initiation of a call to extend said subscriber's line to an idle one of said trunk lines, a message register associated with said calling subscriber's lines, means to operate said message register, restoring means for said automatic switch, and means to put said restoring means into operation as soon as said message register is operated.
- 10 16. In a telephone exchange system, a calling subscriber's line, outgoing trunks, an automatic switch, means to operate said automatic switch to extend said subscriber's line to an idle one of said trunk lines, a toll device associated with said calling subscriber's line, contacts controlled by said toll device, means to operate said toll device, restoring means for said automatic switch, and a circuit for said restoring means extending through said contacts of said toll device.
- 15 17. In a telephone exchange system, a calling subscriber's line, outgoing trunks, an automatic switch, means to operate said automatic switch in response to the initiation of a call to extend said subscriber's line to an idle one of said trunk lines, a toll device associated with said calling subscriber's line, means to operate said toll device, restoring means for said automatic switch, means to operate said restoring means when a calling subscriber abandons the call prior to its completion, auxiliary restoring means for said automatic switch, and means to put said auxiliary restoring means into operation as soon as said toll device is operated.
- 20 25 In witness whereof, I hereunto subscribe my name this 22nd day of July, A. D. 1921.
- ALBEN E. LUNDELL.
